UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

VOTING MECHANISM FOR VOTING-MACHINES.

1,105,597.

Specification of Letters Patent.

Patented Aug. 4, 1914.

Application filed July 28, 1909. Serial No. 509,991.

To all whom it may concern:

Be it known that I, CHARLES C. ABBOTT, a citizen of the United States, residing at Pittsfield, county of Berkshire, State of 5 Massachusetts, have invented an Improvement in Voting Mechanism for Voting-Machines, of which the following is a specification.

This invention relates to the portion of 10 the mechanism of a voting machine which has to do with the casting of the votes, and I have shown it as applied to a horizontal machine, so called, in which the names of party candidates are placed in horizontal 15 lines called party lines and the names of all candidates for the same office are placed in vertical columns, called office lines or columns, although of course the mechanism may be arranged otherwise if preferred.

20 The general object of the invention is to provide voting mechanism that will render it easy for the voter to vote for the candidates of his choice whether in one or in a plurality of party lines, will protect the 25 voter against knowledge by others as to how he has voted and will render it impossible for the voter to vote fraudulently.

It is one of the objects of the invention to 30 render it impossible to place the entire pull of a party lever upon a voting member to move the same from the non-voting to the voting position; in other words, to protect the voting members against injury by means of power applied to a party lever. In carrying out this portion of my invention I 35 have especially provided for two different conditions. One is, where one or more office lines are disconnected from the party levers so that when party levers are operated the 40 disconnected office lines will not be affected. This is necessary in using a cumulative voting attachment where additional office lines are used, some of which are not connected to party levers; also in case of nomination 45 by petition, where one slack is placed in the interlocking members of two office lines, one line having the regular party nominees and being connected to the party levers, the other line having the petition nominees and being 50 disconnected from the party levers. I have also provided for a condition in which no

provision is made for disconnecting the office lines from the party levers.

With the above and other objects in view, I have devised the novel mechanism which 55 I will now describe, referring to the accompanying drawings forming a part of this specification and using reference characters to indicate the several parts.

Figure 1 is an elevation partly broken 60 away showing the voting mechanism assembled, the parts being in the normal position, that is before any of the mechanisms of the machine have been operated; Fig. 1^a is an elevation of the machine as a whole 65 looking at the rear or voting face thereof. Fig. 2 a section on an enlarged scale on the line 2—2 in Fig. 1, certain of the parts being omitted for the sake of clearness in illustration; Fig. 3 a detail elevation showing one 70 party line in the voted position, the cam bar being in the raised position and the catches having been raised to unlock the party lines; Fig. 3^a a detail plan view corresponding with Fig. 2, on an enlarged scale; Fig. 75 3^b a detail view of the link detached; Fig. 4 a section on the line 4—4 in Fig. 3; Fig. 5 a detail elevation on an enlarged scale of the lower party line, the position of the parts corresponding with Fig. 1; Fig. 6 a 80 section on the line 6—6 in Fig. 5; Fig. 6^a a detail plan view on an enlarged scale; Fig. 6^b a detail elevation on an enlarged scale, the point of view being the reverse of that in Fig. 5; Fig. 7 a detail elevation showing 85 an interlocking member and the mechanism connecting the releasing and restricting mechanisms, the parts being in the unlocked position; Fig. 7^a a detail view illustrating the operation of a voting member upon an 90 interlocking member; Fig. 8 a plan view of a portion of the restricting mechanism corresponding with Fig. 7; Fig. 9 a detail elevation showing a restricting arm connected to the restricting bar and in the restricting 95 position, the point of view being the reverse from Fig. 7; Fig. 10 a similar view, the parts being in the non-restricting position; Fig. 11 a similar view, the double arm being locked out of operative position; Fig. 12 an 100 elevation with framework in section showing the connection of a voting member with

a party bar and a restricting bar; Fig. 13 an elevation as seen from the right in Fig. 12; Fig. 14 a detail elevation, which see in connection with Fig. 12, showing a voting member disconnected from the party bar, and also showing portions of the restricting and releasing mechanisms; Fig. 15 a detail elevation as seen from the right in Fig. 14 (see in connection with Fig. 13); Fig. 16 a section on the line 16—16 in Fig. 15 looking in the direction of the arrows; Fig. 17 a detail plan view corresponding approximately with Fig. 2 illustrating a modified form of the invention; Fig. 17^a a view corresponding approximately with Fig. 3^b showing the modified form of link detached; Fig. 18 a detail elevation pertaining to the same modification and corresponding approximately with Fig. 1, the parts being in the normal or locked position; Fig. 18^a a detail sectional view; Fig. 19 a view similar to Fig. 18 showing the position of the parts when a party line has been voted; Fig. 20 a similar view showing the position of the parts when a split vote has been cast, or there has been scratching; Fig. 21 a detail elevation corresponding approximately with Fig. 3 illustrating another modified form of the invention, the parts being in position to illustrate a split vote or scratching, so called; Fig. 22 a similar view illustrating the position of the parts when a party vote has been cast; and Fig. 23 is a similar view corresponding approximately with Fig. 1 showing the parts in their normal or locked position, that is before any of the mechanisms of the machine have been operated.

30 denotes the individual voting members as a whole, which I shall hereafter refer to as voting members. Each voting member comprises a number of parts which will be hereafter specifically indicated by numbers.

31 denotes the party bars which correspond in number with the party lines of the machine, 32 the resetting bars which correspond in number with the party bars and 33 a special resetting bar for the releasing mechanism and for a locking bar 34.

35 denotes an operating bar for the resetting mechanism and 36 a cam bar which is actuated by the entrance mechanism previous to the casting of a vote. The entrance and exit operating mechanism is not shown as specifically it forms no portion of the present invention. The cam bar is provided with a plurality of vertical slots 37, with a plurality of vertical and inclined slots 38 at its upper end in alinement with slots 38 at its lower end in alinement with slots 38 with a similar slot 39 having at its upper end an enlargement 40 relating to the question mechanism (not shown) and at its lower end with a similar slot 41 having at its lower end an enlargement 42 to permit movement of special resetting bar 33 by the resetting lever, presently to be described.

43 denotes the framework of the machine which is formed from plates of sheet metal formed to shape and riveted together. Wherever necessary special portions of the framework will be indicated by specific numbers. The various bars of the machine, both vertical and horizontal, are supported and guided by the various horizontals and other parts of the framework. The party bars and the resetting bars are connected to the cam bar by means of double links 44 which slide between brackets 45 which are riveted to the framework, cotter pins 46 retaining the links against lateral movement. The connection of the links to the party bars and the resetting bars is by means of pins 47 which pass through slots 48 in the party and resetting bars and are fixed in the double links. The connection between the double links and the cam bar is by means of rollers (see dotted lines Figs. 1, 3 and 5), which are carried by pins 49 and engage slots 38 in the cam bar. Brackets 45 also serve as guides for the cam bar. Special resetting bar 33 is connected to the cam bar by means of a double link 190 which straddles the bar, is pivoted to said link as at 191, slides between brackets 45 and is provided with a pin 49 carrying a roller which engages slot 41 in the cam bar. 95

50 denotes latches which are pivoted, as at 51, to brackets 52 riveted to cross pieces 53 themselves riveted to the framework. The latches are provided with pins 54 which engage vertical slots 37 in the cam bar. The forward ends of the latches are provided with offsets 55 which rest upon the upper edges of the party bars and are adapted to coact with shoulders 56 on dogs 57 rigidly secured to the party bars to lock the party bars until the latches are raised, as will presently be more fully explained. 58 denotes similar dogs rigidly secured to the resetting bars. Dogs 57 and 58 are both provided with slots 48 corresponding with the slots in the party and resetting bars and pins 47 pass through the bars, the dogs and the double links. 100

59 denotes double bell crank levers pivoted on pins 189 supported by the framework and cross pieces 53 (see Fig. 4). One arm of each lever is provided with a cross-pin 60, shouldered in practice, which lies in a slot 61 in operating bar 35, the branches of the arm straddling the bar. The other arm of each lever is provided with a cross pin 62 which engages and is engaged by arms 63 and 64 which project respectively from dogs 57 and 58 on the party and resetting bars. 115 120 125

65 is the question controlling bar which is operated by means of the cam bar; but the connections are not illustrated in detail and will not be further referred to, as they form no portion of the present invention. 130

- 66 denotes the resetting shaft which is journaled in the framework and carries a resetting lever 67 lying outside the case of the machine.
- 5 68 is a crank on shaft 66 which is connected to operating bar 35 by means of a link 69 made double in practice.
- 10 70 denotes a cam plate which is riveted to bar 35 and coöperates with an outwardly extending lug 71 on a plate 72 which is riveted to special resetting bar 33, to retract said bar, that is move it toward the right, when operating bar 35 is pulled down by operation of the resetting lever, the movement of bar 33 toward the left being caused by the upward movement of the cam bar, or by operation of the resetting lever, all of which will be more fully explained.
- 15 73 denotes a cam plate which is riveted to special resetting bar 33 and coöperates with an inwardly extending lug 74 on a plate 75 which is riveted to vertical locking bar 34 to force said bar downward should it not drop by gravity when released by catches 109, presently to be described, when special resetting bar 33 is moved toward the right.
- 20 188 denotes a guide for operating bar 35 which is rigidly secured to a portion of the framework.
- 25 30 76 denotes the party levers which are pivoted between broadly U-shaped brackets 77 themselves riveted to the framework. The outer arm of each party lever extends through a slot 78 in the back plate 79, the central portion of each lever being struck upon a curve that will always fill the slot. The outer arms are provided with recesses indicated by a dotted line in Fig. 2 to receive a card bearing the name of the party which is exposed through a slot 80 in the arm. The inner arm of each party lever, indicated specifically by 81, extends through a slot 82 in the corresponding resetting bar and through a slot 83 in a link 84, slot 82 being elongated to permit movement of the resetting bar independently of the party lever, as will be more fully explained, and the slot in the link permitting return movement of the lever without producing sufficient movement of the link to unlock the wedge system, presently to be explained. Each link is connected to the corresponding party bar 31 by means of a stud 85, shown as flattened, which is riveted in a slot 145 in the link (see Fig. 3^a in connection with Fig. 3^b) and passes through a slot 86 in the corresponding resetting bar, said slot being elongated to permit independent movement of the resetting bar. In the present instance, I have shown studs 85 as extending through slots in the party bars which just receive them and as provided with cotter pins 87 passing through the ends of the studs to retain the party bars in place. The left end of each link 84 is loosely connected to a wedge plate 88. Each wedge plate is provided on both upper and lower sides with inclines 89 at its rear ends and inclines 90 at its forward ends. These inclines engage wedge plates 91 which are provided with corresponding inclines causing them to be raised by inward movement of wedge plates 88, *i. e.* movement toward the left. I have shown the links and wedge plates 88 as connected by means of T-shaped lugs 92 on the links which engage correspondingly shaped recesses 93 in the wedge plates, said recesses being provided with necks of greater width than the necks 94 of the lug, said necks and recesses being so shaped as to permit upward and downward movement of the wedge plates when the links and wedge plates are moved laterally. Wedge plates 91 are provided with central angular recesses 95 which receive blocks 96 rigidly secured to uprights of the framework, the recesses being of greater height than the blocks so as to permit free vertical movement of the wedge plates. The upper wedge plate 88 engages a fixed wedge plate 97 having inclines corresponding with the upper inclines 89 and 90 on the upper wedge plate 88. Fixed wedge plate 97 forms a stop for the upper end of the wedge system. The wedge plates are shown as covered by a plate 98 which is firmly riveted in place and is provided with a flange 99 having slots in which the left ends of the resetting bars 100 slide.

an angular notch 111 see Fig. 5, which receives a flat stud 112 lying between the arms of catch 109 and serving as a space block, lugs at the ends of said stud passing through 5 and being headed down on the outer sides of the arms.

113 denotes a plate rigidly secured to each resetting bar 32 and having at its right end as seen in Figs. 1 and 5 a projection having 10 notches 114 adapted to be engaged by the cross piece of the corresponding catch to lock the resetting bar in its normal position and also to lock the voting members as will be more fully explained, and at its left 15 end an inclined arm 115 the end of which is offset as at 116 to bring it into its plane of engagement as will presently be described. The inclines and notches may be formed by cutting away the metal of the bars if preferred. At the left end of double catch 109 and extending from one side thereof is an arm 117 (see Fig. 6^a) having a head 118 which is adapted to be engaged by offset 116 of arm 115. 119 denotes another arm extending 20 from the left end of double catch 109 which is provided with a hook 120 which engages a slot 121 in a dog 122 pivoted to a bracket 123 extending from one of the U-shaped brackets 77. A tooth 124 on dog 25 122 is adapted to engage a notch 125 in the corresponding link 84 for a purpose presently to be explained.

126 denotes the restricting shaft and 127 (see Fig. 14) the restricting lever which lies 30 outside the framework of the machine on the front.

128 denotes an arm keyed or otherwise secured to the restricting shaft and 129 a link connected to arm 128 by a pivot 197 and to 40 another link 130 by a pivot 196. See Figs. 1, 5 and 7.

131 denotes the releasing shaft and 132 the releasing lever.

133 is a double bell crank lever keyed or 45 otherwise secured to releasing shaft 131, and comprising double arms 134 and 135. The branches of arm 133 straddle locking bar 34 and carry a pin 136 which passes through a slot 137 in the locking bar. The branches 50 of arm 135 straddle the right end wedge bar 103 and carry a pin 138 on which link 130 is pivoted and which passes through a slot 139 in wedge bar 103.

140 denotes a lip at the left end of special 55 resetting bar 33 which is adapted to be engaged by a lug 141 on the right end of the wedge bar.

142 denotes a lug which projects from link 60 130 and is adapted to be engaged by lip 140 on the special resetting bar.

143 denotes an extension of locking bar 34 which extends upward to an opening 144 in back plate 79. At the upper end of the extension is a hook 146 which extends through 65 opening 144 and down over the back plate in

position to be engaged by a projection 147 on actuating slide 148 which operates the paper feed mechanism (not shown).

149 denotes the shutter openings and 150 the independent shutters.

The shutter operating mechanism is not illustrated and described in detail as specifically it forms no portion of the present invention. It is sufficient for the purposes of this specification to say that the operation of a party lever or the releasing lever raises locking bar 34 and extension 143 with its hook 146 which permits actuating slide 148 to be moved toward the left, thus enabling the voter to open the independent shutters. 70 When a shutter is opened projection 147 on the actuating slide is carried under the hook of extension 143 which retains locking bar 34 in the raised position and also locks the resetting lever as will be more fully explained. When the machine is reset by operation of the exit mechanism (not shown), when the voter leaves the machine, extension 147 is withdrawn from under hook 146 which releases the locking bar. 80

The voting members 30 comprise oscillatory shafts journaled in the framework and having voting levers 151 lying outside the machine at the back. Each voting member is provided with two parallel arms indicated respectively by 152 and 154, with a lug 155 which is adapted to engage a cam plate of an interlocking member 156 and with a lug 153 parallel with lug 155, the functions of which will presently be explained. Between arm 154 and lug 153 is a slot 194 in which the resetting bar 32 lies and between arm 152 and lug 153 is a slot 195 in which the party bar 31 lies. The interlocking member used is the one illustrated and described in my former Letters Patent No. 900,905, dated October 13, 1908, and comprises cam plate 157, side plates 158, see Figs. 7 and 7^a, and stud and slot connections between said plates acting to 95 shorten the member when a cam plate is moved laterally. When a voting member is actuated, the lug 155 of said member engages a cam plate of the corresponding interlocking member, forces said cam plate 100 laterally shortening and imparting rigidity to the member and locking all of the other cam plates so that under ordinary conditions no other voting member in that column can be operated as it will be locked in the non-voting position by the corresponding cam plate of the interlocking member. The 105 number of interlocking members in the machine corresponds with the number of columns of names of candidates. 115

159, see Figs. 7, 9, 10 and 11 in connection with Figs. 1 and 14, denotes the restricting members which lie in a horizontal line below the lower line of voting members and comprise oscillatory shafts journaled in 130

the framework in the same manner as the voting members. Each restricting member is provided with a lug 160 which is adapted to engage a cam plate 157 of an interlocking member in the same manner that it is engaged by lugs 155 of the voting members. Each restricting member is also provided with arms 161 between which a dog 162 is pivoted, see Figs. 1 and 14. These dogs extend upward through slots 163 in a plate 164 secured to the framework of the machine. The function of these dogs is to engage lugs 153 on the voting members of the lower office line to lock them out of operative position, as clearly shown in Fig. 7 (which see in connection with Fig. 5) all of which will presently be more fully explained.

Turning now to Figs 12 to 16, inclusive, 20 165 denotes pins having heads 166 comprising coils which inclose the voting member shafts and retain the pins thereon leaving the pins free to slide. These pins may be moved in and out by hand but are preferably operated by a special tool (not shown). 25 167 denotes a locking slide having flanges 168 which are adapted to engage the inner coils of the pins to lock them in their normal or engaging position or in their disengaging position. The locking slides, which correspond in number with the lines of voting members, are provided with slots 169 and are supported by flattened studs 170 which engage the framework and pass through the 30 slots and washers 171, the slides being held in place by cotter pins 172. The forward ends of the operative portions of the pins lie in slots 173, the forward ends of said slots acting as stops to limit the outward movement of the pins. The function of these pins is to connect the voting members with the party and resetting bars, movement of a party bar actuating the voting members of that party line, and locking of 40 the resetting bars locking the voting members. In the normal position of the parts, the pins pass through lugs 154 on the voting members, through slots 193 in the resetting bars and through slots 192 in the party 45 bars, see Figs. 1, 2 and 3, and the ends thereof engage sockets in lugs 152 on the voting members as clearly shown in Fig. 12. In the normal position of the parts, the locking plates lie in front of the inner coils of 50 the pins and lock them against retraction. In Fig. 14, the pin has been retracted to disconnect the party bar from the voting member and it is locked in the retracted position by the engagement of a flange 168 of the 55 locking plate with the inner coil of the pin which lies back of it. The locking slides are provided with recesses 174 which permit the flanges to be moved out of alinement with the inner coils of the pins and are 60 locked in the locking position by means of 65

latches 175 which engage flanges 176 at the inner ends of the slides (see Figs. 15 and 16).

Turning now to Figs. 7 to 11, inclusive, 177 denotes an arm extending from restricting shaft 126 at an angle to arm 128. 178 denotes a link the left end of which is curved as clearly shown in Fig. 7 and which is pivoted to arm 177 and to restricting bar 179. The restricting bar is provided with 70 slots 180. The restricting members carry double arms 181 which are keyed to the shafts of the members, straddle the restricting bar and are provided with corresponding holes 186 and 187 in the two branches. 80 182 denotes holes in one of the horizontals of the framework and 183 pins which are adapted to pass through either of the holes in double arms 181 and through slots 180 in the restricting bar or through holes 182 in the horizontal of the framework. One of the branches of each double arm is provided with an extension 184 to which a swinging spring latch 185 is pivoted. This latch may be swung aside to permit the removal of a pin from either a slot in the restricting bar or a hole in the horizontal and the corresponding hole in arm 181 and its transfer to the other position. Fig. 9 shows the position of the parts when a 90 double arm is connected to the restricting bar and the bar has been moved toward the right to the restricting position, the pin passing through hole 186 in the branches of the double arm and a slot in the restricting 95 bar and being locked in place by the spring latch. Fig. 10 shows the position of the parts when the restricting bar is in its normal or non-restricting position. (See also Figs. 7 and 14 which show the same position of the parts.) Fig. 11 shows the position of the parts when a restricting member is in the non-restricting position and is locked against operation. The pin has been removed from the slot in the restricting bar 100 and hole 186 in the double arm and has been passed through hole 187 in the double arm and a hole 182 in a horizontal of the framework and locked there by the spring latch. 105 The machine is of course normally locked. 110 This position of the parts is shown in Figs. 1, 2, 5 and 6. The first act of a voter is to operate entrance mechanism (not shown) to unlock the machine. The operation of the entrance mechanism raises cam bar 36 from 115 the position shown in Figs. 1 and 5 to the position shown in Fig. 3. As the cam bar moves upward the rollers on pins 49 will travel toward the left in slots 38 and 41 and will carry double links 44 and 190 toward 120 the left. This movement will have no effect on party bars 31 and resetting bars 32 for the reason that pins 47 will travel toward the left in the slots 48 in the party and resetting bars. Link 190, however, is pivoted to 125 130

special resetting bar 33 and will therefore move said bar toward the left. In the normal or locked position of the machine, the offsets 55 of latches 50 will lie in front of shoulders 56 on dogs 57 (see Figs. 1 and 5). The dogs are moved to this position through the engagement of pins 54 with the upper ends of slots 37 in the cam bar by the downward movement of said bar when the exit mechanism (not shown) is operated by a voter leaving the machine. The function of these latches is to lock the party bars against movement by the party levers until after the position of the parts is such that the counters (not shown) will be engaged by operated voting members, specifically until the counter pins (not shown) are in position to be engaged by the counter dogs. This mechanism is omitted for the sake of clearness as it forms no portion of the present invention. During the latter portion of the upward movement of the cam bar caused by operation of the entrance mechanism, pins 54 will be engaged by the lower ends of slots 37 in the cam bars and the latches will be raised as in Fig. 3, leaving the party bars unlocked and subject to operation by the party levers.

The voting operation.—Let us suppose, first, that the voter desires to vote a straight party ticket; second, that he desires to scratch or split; and, third, that he desires to vote for a portion only of the offices to be voted for or scattering, or independently. The inner arm 81 of each party lever 76 passes through an elongated slot 82 in the corresponding resetting bar and through a slot 83 in a link 84 which is connected to a flattened stud 85 lying in an elongated slot 86 in the resetting bar and engaging the party bar, it being understood that while the party bars (as viewed in Figs. 1 and 3) lie in front of the resetting bars the links lie back of the resetting bars, the party bars not extending as far to the left as the resetting bars which are extended to engage primary locking bars (not shown). When a party lever is operated, *i. e.* pulled, the corresponding party bar is operated which carries all the voting members in that party line to the voting position and causes the lugs 155 of the voting members, see Fig. 7^a, to engage cam plates of the corresponding interlocking members, the effect of which is to shorten the interlocking members and impart rigidity thereto thereby locking the voting members in all other party lines and also the independent voting mechanism in the non-voting position. The movement of the link 84 toward the left by the party lever causes said link to move the corresponding wedge plate 88 toward the left, the effect of which is to raise the wedge plates 91 and the other wedge plates 88 of the system and to lock the wedge system, as

already explained, thereby locking all of the other party levers in the non-voting position and rendering it impossible to place any strain on any portion of the voting mechanism and to cast a fraudulent vote. The 70 voted position of a party line is shown in Fig. 3. The first portion of the voting movement of a party bar carries the corresponding wedge plate 88 toward the left far enough to take up the entire slack in 75 the system of wedge plates and thus lock all other party levers, the full travel of the operated party lever and party bar carrying the wedge plate 88 to the position shown. This locking of the wedge system and party 80 levers in practice takes place during the first sixteenth of an inch travel of the party bar. In practice, owing to the slots 192 in the party bars through which the pins 165 of the voting members pass, the party bar 85 travels three-sixteenths of an inch, more or less, before it commences to operate the voting members. At this point the incline 107 on the party bar will have traveled toward the left from the position shown in Figs. 1 90 and 5 toward the position shown in Fig. 3. Further movement of the party bar by the party lever causes catch 109 to ride up incline 107 clearing the notches 114 on the resetting bar and leaving said bar unlocked. 95 An instant later offset 116 on arm 115 of plate 113, see Figs. 6^a and 6^b, comes in contact with head 118 of arm 117 extending from double catch 109 which gives a relatively faster travel to the catch and quickly 100 carries it to the position shown in Fig. 3. The last effect of this movement is to unlock all other party lines and the independent voting mechanism permitting split voting. This unlocking does not take place, 105 however, until the slack is taken out of the interlocking members, and they are rendered rigid, so that it is impossible at this moment to operate a voting member in some other party line and thus secure a fraudulent vote before finishing the party vote. As soon as the catch 109 corresponding with the operated party bar starts up the incline 110 it commences to raise locking bar 34, through the engagement of stud 112 with notch 111 115 in the locking bar (see Fig. 5). The first portion of the movement, however, does not raise the catches 109 of the other party lines, which are not raised until the locking bar has moved upward sufficiently to cause the lower sides of notches 111 to engage the corresponding studs 112. The last portion of the upward movement of the locking bar is very quick owing to the short distance from the stud 110 on which the catch 120 is pivoted to stud 112 which raises the locking bar. This last portion of the upward movement of the locking bar is caused, as already explained, by the engagement of offset 116 with head 118 upon the catch. 125

When the locking bar is raised by the operation of a party lever, extension 143 is raised also and the hooked upper end 146 of said extension is raised above projection 147 on the actuating slide 148 which operates the feeding mechanism of the independent voting strip (not shown). The opening of a shutter 150 for independent voting carries actuating slide 148 toward the left, projection 147 passing under hooked end 146 which has been raised as already described, from the position shown in Fig. 1, thus retaining the extension and the locking bar in the raised position, from which position it can not be returned until the exit mechanism is operated by the voter on leaving the machine. It will of course be understood that the interlocking member prevents the opening of an independent shutter until the regular voting member corresponding with that shutter has been moved from the voting to the non-voting position. This is not illustrated in this application for the reason that specifically it forms no portion of the present invention, it being deemed sufficient for the purposes of this specification to show how the independent voting mechanism is unlocked by operation of locking bar 34. Having cast a straight party vote the voter should he desire to scratch any of the candidates of his party does so by unvoting the voting members corresponding with the candidates for whom he does not desire to vote; that is, he moves the voting members corresponding with the candidates for whom he does not desire to vote from the voting position to which they have been moved by the party lever and party bar to the non-voting position. Should he desire to split, that is, cast votes for candidates of another party, he does so by moving the corresponding voting members from the non-voting to the voting position. It will of course be understood that having scratched a candidate, that is unvoted a vote already cast, he relieves the tension on the corresponding interlocking member so that a vote may be cast for the candidate of any other party for the same office.

In order to prevent a voter who has voted a party ticket and then split upon one or more candidates of his party from afterward operating the same party lever again and putting the entire force of the party lever upon a single voting member and the resulting danger of injury to the machine and the possibility of getting in an extra vote, dogs 122 are provided. These dogs engage notches 125 in the links 84 corresponding with actuated party bars, and are provided with slots 121 which are engaged by hooks 120 of arms 119 extending from catch 109. When the party bar is moved toward the left by operation of the party lever, the cor-

responding link 84 moves to the left beyond dog 122 before catch 109 will permit the dog to drop down far enough to engage the notch, but when a voter scratches a candidate for whom he has already voted, the return of the corresponding voting member from the voting to the non-voting position will, through the engagement of the pin 165 of the voting member with the slot 192 in the party bar move said bar to the right far enough to permit the dog to engage the notch 125 in the link 84 and thus render it impossible to again operate the party bar by means of the party lever until after the mechanism has been re-set, as by operation of the cam bar when the voter leaves the machine or by operation of the resetting lever presently to be described. Nor can the voter operate any other party lever, for the reason that after a party lever has been operated and the party bar and link 84 have been moved far enough toward the left to cause the corresponding wedge plate 88 to take up the slack in the wedge system, it is impossible to withdraw wedge plate 88 to its original position for the reason that the movement of a party bar toward the right by the operation of scratching does not withdraw the wedge plate far enough to release the wedges of the system and return of the party lever to its normal position will not draw back the wedge plate far enough to release the wedges of the system owing to the length of the slot 83 in the link 84 through which the inner arm of the party lever passes.

The releasing mechanism.—Should a voter not wish to vote any party ticket but prefer to vote scattering for the candidates of different parties or to vote for candidates for a part only of the offices to be voted for, he is not obliged to operate a party lever 76 but may operate releasing lever 132, the effect of which is to lock all the party levers and to unlock all the voting members; in other words, a voter has the option of operating a party lever and voting a straight ticket and then scratching or splitting if he chooses or of operating the releasing lever and then voting scattering for a portion or all of the offices to be voted for. Operation of the releasing lever oscillates shaft 131 and bell crank lever 133. Pin 138 carried by arm 135 of the bell crank lever is at the left end of slot 139 in wedge bar 103 and pin 136 carried by arm 134 of the bell crank lever is at the upper end of slot 137 in locking bar 34. Wedge bar 103 is moved toward the left which locks the wedge system and makes it impossible to operate any party lever. Simultaneously with the movement of the wedge bar the locking bar is raised, and an instant after the locking of the party levers by means of the wedge system studs 112 carried by double catches 109 will be en-

gaged by the lower walls of notches 111 in the locking lever and continued movement of the releasing lever and the locking bar 34 will raise all of the catches 109 and release 5 the party bars, leaving all the voting members and the independent mechanism free to be operated. By insuring the locking of all party levers before the party bars and voting members are released, it is rendered impossible 10 to partially operate the releasing lever, then operate a voting member and then pull the party lever of some other party line, which would put the entire force applied to the party lever upon the voting member 15 operated and might result in the casting of a fraudulent vote or in serious injury to the machine; in other words, the present construction renders the casting of a fraudulent vote and injury to the machine practically 20 impossible. Furthermore, when the releasing lever is fully operated catches 109 through hooks 120 on arms 119 forming a part of the catches will permit the corresponding dogs 122 to drop into the notches 125 of links 84, thereby locking said links and doubly locking the party levers. It will be seen that after the releasing lever has been operated it will be impossible to return the same and unlock the party levers or to 30 lower locking bar 34 as the pin and slot connections between bell crank lever 133 and wedge plate 103 and between said lever and the locking bar render this impossible, pins 138 and 136 merely moving in slots 139 and 137 in the wedge bar and locking bar when the releasing lever and bell crank lever are operated, but without imparting movement to the wedge bar and locking bar which remain in the position to which they have 40 been moved by the operative movement of the releasing lever. In other words, the releasing lever having been operated to perform the releasing movement just described cannot be again operated to return the parts 45 to their normal position. This can only be done by operation of the resetting lever presently to be described. It will be obvious furthermore that after a party lever has been operated and the locking lever has been 50 raised the releasing lever will be powerless as oscillation thereof will merely cause pins 138 and 136 to move in the slots in wedge bar 103 and the locking bar but without imparting any movement thereto.

55 *The resetting mechanism.*—This mechanism is provided in order to enable a voter who has operated the wrong party lever or made a mistake of any kind or who desires to return all operated voting mechanism to 60 its normal or non-voting position without operation of the counters to do so by operation of resetting lever 67. The effect of this would be to reset the voting members and the party levers and to unlock the wedge system, which would be otherwise impossi-

ble as the returning of the voting members to their non-voting position, *i. e.* scratching, would not unlock the wedge system and enable him to operate another party lever. The resetting lever is rigidly secured to resetting shaft 66 which extends through the face plate and lies on the back of the machine. Operation of the resetting lever by means of crank 68 and double link 69 draws down operating bar 35 which is provided with slots 61 corresponding with the party lines. When a party bar is operated the corresponding double bell crank lever 59 is moved from the position shown in Figs. 1 and 5 to the position shown in Fig. 3 by 70 means of the arm 63 which extends from dog 57 rigidly secured to the party bar and engages the cross pin 62 carried by the bell crank lever. This does not change the position of the operating bar, but carries cross pin 60 to the upper end of slot 61 so that when the resetting lever is operated the operating bar will swing the bell crank lever back to the position shown in Figs. 1 and 5. In the normal or reset position of the parts 75 the arms 63 and 64 which extend from dogs rigidly secured to the party and resetting bars are in alinement with each other as in Figs. 1 and 5. When a party bar is operated the corresponding arm 63 will be moved 80 forward out of alinement with arm 64 as indicated by dotted lines in Fig. 3. Should the releasing lever be operated, however, instead of a party lever, arm 63 would remain in its normal position as in Figs. 1 and 5, but 85 the arm 64 would be engaged and the resetting bar carried forward by the operation of a voting member. No matter what position may be taken by the party and resetting bars, when operating bar 35 is pulled down 90 by operation of the resetting lever, the party and resetting bars will be returned to their normal position through the engagement of pins 62 on bell crank lever 59 with the arms 63 and 64. As the two arms of the 95 bell crank lever lie on opposite sides of the party and resetting bars and the arms, it is rendered practically impossible for the parts to get out of alinement and fail to work properly. The downward movement of the 100 operating bar, position not shown, also acts to move special resetting bar 33 toward the right through the engagement of cam plate 70, see Figs. 1 and 5, on the operating bar with lug 71 on plate 72 which is rigidly secured to bar 33. This movement is permitted by enlargement 42 of slot 41 in the cam bar in which the roller on pin 49 on link 190 now lies. The special resetting bar in turn acts to return locking bar 34 to its 105 normal position through the engagement of cam plate 73 on bar 33 with lug 74 extending from plate 75 which is rigidly secured to the locking bar. And furthermore, 110 bar 33 withdraws wedge bar 103, if it has 115 120 125 130

been operated by the releasing lever, or the restricting mechanism, presently to be described, through the engagement of lip 140 on bar 33 with lug 141 on the wedge bar, 5 thus leaving the wedge system unlocked; in fact, leaving the entire machine in its normal position, that is, as it was before the operation of a party lever or the releasing lever. It will be seen that should a voter 10 operate a party lever and afterward desire to change his vote, whether or not there has been splitting, or should he have operated the releasing lever and voted scattering for the nominees of different parties, he can by operating the resetting lever undo all that has been done and 15 reset the mechanism so that he can operate any party lever or vote another scattering ticket, provided, however, that he has 20 not opened an independent shutter. If a voter elects to vote independently, that is, not for the candidates of any party, but upon a ticket of his own making, which he must do by means of the independent voting 25 mechanism which specifically forms no portion of the present invention, he must open one or more of the independent shutters. The opening of an independent shutter moves the actuating slide 148 for the paper feed mechanism toward the left and causes 30 projection 147 to pass under hook 146 on extension 143 of locking bar 34, thereby locking said bar in the raised position and rendering it impossible to release the wedge 35 system and thereby unlock the party levers and render the releasing mechanism operative. That is, it will be impossible for him to operate resetting lever 67 enough to withdraw wedge bar 103 if the releasing lever 40 has been operated or to withdraw wedge plate 88 if a party lever has been operated. In brief, the opening of an independent shutter renders it impossible to unlock the wedge system, which can only be done after 45 the opening of an independent shutter by operation of the cam bar by means of the exit mechanism when the voter leaves the machine. Under ordinary conditions, however, that is when an independent shutter 50 has not been opened, the operation of a party lever 76 or the releasing lever 132 or a voting member 30 does not affect the resetting mechanism with the exception of swinging bell crank levers 59 from the position shown in Fig. 3 to the position shown in 55 Figs. 1 and 5. Should this movement take place, pins 60 would pass to the lower ends of slots 61 in operating bar 35, but without imparting any movement to the bar.

60 *Disconnecting voting members or office lines from the party levers.*—When this has been done it follows that when a party lever is operated to vote a party ticket the office lines or voting members that have been disconnected will not be voted. This is some-

times necessary in using a cumulative voting attachment where additional office lines are used, some of which are not connected to party levers, also in case of nomination by petition where one slack is placed in the interlocking members of two office lines, one line having the regular party nominees and being connected to the party lever, the other line having the petition nominees being disconnected from the party lever. In operation this feature works as follows: Operating the party lever operates the voting members of all the party candidates. Should the voter instead desire to vote for the petition nominees, he would have to scratch the party nominees before he could do so. Should the voter instead of operating a party lever operate the releasing lever, he could then vote for the party or petition nominees as he saw fit. This mechanism is clearly illustrated in Figs. 12 to 16, inclusive. It will be seen in Figs. 12 and 14 that the resetting bar 32 lies in a slot or recess 194 between arm 154 and lug 153 of the voting members and that the party bar 31 lies in a slot or recess 195 between lug 153 and arm 152 of the voting members. In Fig. 12, pin 165 is shown as extending through arm 154 and lug 153 and as engaging arm 152. This is the normal position of the parts and leaves the voting members connected to the party bars and subject to operation by the party levers. The pins 165 are locked in this position by means of locking slides 167 which engage the front side of the inner coils of the pins as in Fig. 12 and lock them against retraction, the slides being locked in place by latches 175 which engage flanges 176 of the locking slides as in Fig. 15. In Fig. 14, the pin 165 is shown as withdrawn from arm 152 of the voting member and from the slot 192 in the party bar and as locked in the retracted position by the locking slide which lies back of the inner coil of the head of the pin. In this position of the parts, the disconnected voting members are wholly free from the party bar and operation of the party bar has no effect upon such disconnected voting members. Should the voter desire, however, after having operated a party lever and voted the connected voting members, he can split and vote the disconnected voting members. When the voter leaves the machine, the resetting bar will return all voted disconnected voting members the same as the connected voting members. To set up the machine and disconnect an office line from the party bars, the custodian would raise the latches 175 and would move the locking slides toward the right (looking from the front of the machine), as shown in Fig. 13, when the pins 165 of the office line to be disconnected would be withdrawn as in Fig. 14.

After the office line or lines has been dis-

connected, locking slides 167 would be returned to their normal position and locked there by the latches.

The restricting mechanism.—The restricting lever 127 lies outside the casing of the machine on the front. This lever is rigidly connected to restricting shaft 126. When a voter of limited franchise approaches the machine, as, for example, a woman who 10 might be permitted to vote only for members of the board of education, the custodian operates the restricting lever, the effect of which is to swing arm 177 from the vertical position as in Fig. 5 to the horizontal position as in Fig. 7, which operates restricting members 159 by means of restricting bar 179 and link 178 which is pivoted to the restricting bar and the curved left end of which is pivoted to arm 177. The restricting shaft 20 also carries arm 128 which is connected to arm 135 of bell crank lever 133 and to wedge plate 103 by means of links 129 and 130, the latter carrying pin 138 lying in slot 139 in the wedge bar and passing through arms 25 135 of the bell crank lever. When the restricting members are operated by the restricting lever, the lugs 160 on the restricting members will engage the corresponding cam plates of the interlocking members, taking 30 the slack out of said members and leaving them rigid and thereby locking the independent shutters and all of the voting members with the exception of the voting members in the lower line, which are in position to act on the same cam plates that have 35 been acted on by the restricting members. The voting members in this lower line, however, are locked by means of dogs 162 which are pivoted to arms 161 of the restricting 40 members. These dogs engage the lugs 153 of the voting members in the lower office line and lock them as in Fig. 7. Thus the voting members of all the office lines are locked when the restricting lever is operated 45 provided that the connection has been made between restricting members 159 and restricting bar 179. Ordinarily the entire voting mechanism of the machine is restricted, *i. e.* connected to the restricting mechanism, with the exception of certain voting 50 members in part of the office lines which may be voted by limited franchise voters. The connection and disconnection of the restricting members with the restricting bar 55 is effected by means of the pins 183 of the restricting members which are adapted to engage the slots 180 in the restricting bar. Fig. 9 shows the position of the parts when the double arm 181 of a restricting member 60 is connected to the restricting bar and the bar has been moved toward the right to the restricting position, the pin passing through the hole 186 in the branches of the double arm and a slot 180 in the restricting bar and 65 being locked in place by spring latch 185.

Fig. 10 shows the position of the parts when the restricting bar is in its normal or non-restricting position, and Fig. 11 shows the position of the parts when the restricting member is in its non-restricting position 70 and is locked out of operation. The pin has been removed from hole 186 in the double arm and from the slot in the restricting bar and has been passed through hole 187 in the double arm and a hole 182 in a horizontal 75 member of the framework and locked thereby by the spring latch. It will be obvious that operation of the restricting lever will lock all the voting members corresponding with, that is, in vertical alinement with, restricting members connected to the restricting bar as in Figs. 9 and 10 and will have no effect on voting members in vertical alinement with the restricting members locked out of operative position as in Fig. 11. 80

It will be remembered that the ordinary voter, that is, a voter with unrestricted franchise, has the option of operating a party lever and voting a party ticket or of operating the releasing lever and voting scattering. In the case of a restricted voter, however, the party levers are locked by operation of the restricting lever and it is desirable that the restricted voter should not be compelled to operate the releasing lever as 95 it would necessitate an additional operation, but that the restricted voter should be enabled to vote for the candidates to which he or she is entitled to vote with the least possible trouble. This result is accomplished as 100 follows: When the custodian operates the restricting lever on the approach of a voter with limited franchise, he causes lug 142 on link 130 to be moved from the position shown in Fig. 5 into engagement with the lip 140 at the left end of special resetting bar 33, the position of links 129 and 130 being intermediate the position in Fig. 5, and that in Fig. 7 and the pivot 196 connecting the links being above a line intersecting the point of engagement of lug 142 with lip 140 and the center of pivot 197 connecting link 129 with arm 128 on the restricting shaft. When the voter operates the entrance mechanism and raises cam bar 36, special resetting bar 33 will be moved toward the left by means of double link 190 and the roller carried by a pin 49 and engaging slot 41 in the cam bar. The effect of this movement of bar 33 will be to move links 129 and 130 from the intermediate position (not shown) to the position shown in Fig. 7 and to move bell crank lever 133 from the position shown in Fig. 5 to the position shown in Fig. 7, which moves wedge bar 103 toward the left and raises locking bar 34 in the same manner as when the bell crank lever is operated by the releasing lever. The movement of the wedge bar locks the wedge system and the party 115 120 125 130

levers and the raising of bar 34 raises catches 109, thereby unlocking the voting members. It will be apparent that owing to the free movement of links 129 and 130 as described the restricting lever and the restricting bar will not be returned to their normal position by the downward movement of the cam bar caused by operation of the exit mechanism when the restricted voter leaves the machine, and so long as restricted voters continue to vote the custodian has nothing further to do. This is a desirable feature, as most voters of limited franchise are women and a number of them usually vote together. As soon as a voter having unlimited franchise approaches the machine to vote, the custodian returns the restricting lever to its normal position thereby throwing off the restriction and leaving the ordinary voting mechanism of the machine in its normal locked position and subject to unlocking by the raising of the cam bar when the entrance mechanism is operated. It will of course be understood that when a restricted voter leaves the machine the lowering of the cam bar by the exit mechanism withdraws wedge bar 103 and lowers locking bar 34 in precisely the same manner as when a voter with unlimited franchise leaves the machine, the only difference being that after a restricted voter has voted if the next voter is a restricted voter no operation of the restricting lever is required, but if the next voter is a non-restricted voter the custodian must return the restricting lever to its normal position and throw off the restriction before the non-restricted voter operates the entrance mechanism and raises the cam bar. It will be obvious that owing to the two link connection (links 129 and 130) between the releasing mechanism and the restricting mechanism operation of the releasing mechanism in ordinary voting will have no effect on the restricting mechanism.

The effect of operation of the entrance and exit mechanisms.—This has been already described in effect in the description of the voting, releasing and resetting mechanisms. It has been made clear that the mechanism of the present application is unlocked and locked by the upward and downward movements of the cam bar and that so far as the present invention is concerned it is immaterial by what specific form of entrance and exit mechanism the cam bar is operated. In Figs. 1 and 5 the parts are at their normal or locked position. Operation of the entrance mechanism raises the cam bar which by means of double links 44 raises latches 50 out of engagement with shoulders 56 on dogs 57 on the party bars and by means of double links 190 moves special resetting bar 33 toward the left, thereby leaving the party levers and lock-

ing bar 34 unlocked, and leaving special resetting bar 33 in position to be operated by resetting lever 67, operating bar 35, cam plate 70 and lug 71 on plate 72 to insure the return of locking bar 34 to its normal position by means of cam plate 73 and lug 74 on plate 75. When the voter leaves the machine he operates exit mechanism which lowers the cam bar to its normal position, as in Figs. 1 and 5. The effect of this movement is, by means of links 44 and 190, to return the party bars, resetting bars and special resetting bar 33 to their normal position by movement toward the right, and also through the engagement of pins 165 of the voting members with slots 192 in the party bars to return all operated voting members to their normal position, to withdraw any operated wedge plate 88 or wedge bar 103, if it has been operated, leaving the wedge system unlocked, to draw down locking bar 34, if it does not drop, and with its extension 143 thereby locking the independent voting shutters, and to lower catches 109, the cross pieces 108 of which engage notched projections 114 on plates 113 on the resetting bars, and also to lower the latches 50 to the locking position, thereby locking the resetting and party bars.

First modified form.—This modification shows a form of locking mechanism adapted to be used where no provision is made for disconnecting the voting members from the party bars and consequently from the party levers, the resetting bars being dispensed with and their functions performed by the party bars. The mechanism is illustrated in Figs. 17 to 20, inclusive, Fig. 17 being a detail plan view showing the modified form of connection between the party lever and the party bar; Fig. 18 a detail elevation, the parts being in a position corresponding with Fig. 1, that is, the party bar being locked; Fig. 19 a similar view showing the position of the parts when a party line has been voted; and Fig. 20 showing the position of the parts when a split vote has been cast. This form of the mechanism is in many respects preferable where it is not required to disconnect the voting members from the party bars. The party lever 76 is pivoted between brackets 77 as before and the wedge system and party bars 31 operate as before. The links corresponding with the links 84 of the other form are numbered 226, and the locking bar 34 of the other form is in this form numbered 227. 198 denotes an extension of the party bar which is riveted between each party bar and a catch plate 202. Each party bar 31 and extension 198 is provided with notches 199, each party bar, party bar extension and catch plate 202 is provided with a slot 200 through which a flattened stud 215 extends, the slot being of sufficient length to permit splitting, and the

extension is provided with a slot 201 to provide clearance for the party lever. Stud 215 is riveted to link 226 and slides in the party bar, the extension and the catch plate.

5 The connection of link 226 with wedge plates 88 is the same as in the other form. 222 denotes an incline on link 226, the functions of this incline and notches 199 being the same as those of notched projections 114

10 and inclines 107 of the other form. 208 denotes a pawl pivoted on a stud 212 which is fixed in one of the horizontals of the framework 43, extends through a slot 228 in locking bar 227 and carries a washer 229 outside

15 of the locking bar, for which it serves as a guide. Pawl 208 is provided with an upwardly extending arm 209 which is engaged by an inwardly turned lug 205 on catch plate 202, as will be more fully explained.

20 210 denotes a rounded recess in pawl 208 which is engaged by a rounded projection 230 on a lug 211 which is pivoted on a stud 213 seated in a bracket 224 which is riveted with brackets 77 to a suitable portion of the

25 framework. 214 denotes a pin extending from pawl 208 and engaging an opening 221 in locking bar 227, said opening being larger than the pin for a purpose presently to be explained. Catch plate 202 is provided with

30 an opening 203 to clear stud 212 and pin 214. 223 denotes a projection on the link shown in the present instance as formed at the right end of a notch 225, the purpose of which will presently be explained. 216

35 denotes a counterweight, the function of which is to balance locking bar 227. This weight is carried by a lever 217 pivoted as at 218 to a bracket 220 which is rigidly secured to the framework. The end of the

40 lever opposite to the counterweight is pivoted to the locking bar as at 219. The operation of this modification is briefly as follows: In Fig. 18, the party bar 31 is shown at its extreme position toward the right, which is the locked or non-voted position of the machine, locking bar 227 being at its normal position after having returned pawl 208 to the locked position. Should a voter pull a party lever, the party bar, the party

45 bar extension, the link and the catch plate will be moved toward the left and the pawl will ride up incline 222 on link 226 clearing notches 199 on the party bar and the party bar extension. Further travel of the operating catch toward the left will cause lug 205 thereon to engage arm 209 of the pawl and will lift the pawl from the position shown in Fig. 18 to the position shown in Fig. 19. The movement of the operated

50 pawl raises locking bar 227 through the engagement of pin 214 with the upper wall of the corresponding opening 221 in the locking bar and the locking bar in turn through the engagement of the lower walls of the

55 other openings 221 therein with the pins

214 upon the other pawls will raise the other pawls out of engagement with the notches 199 in the corresponding party bars and extensions leaving all the party bars and consequently all the voting members unlocked. It should be noted that the first portion of the upward movement of the locking bar caused by the operated pawl 208 riding up an incline 222 does not disengage the other pawls from the notches of the corresponding party bars and extensions. This is owing to the fact that the openings 221 in the locking bar are larger than the pins 214 on the pawls, consequently the other pawls are not raised until the locking bar has been moved upward far enough to cause the lower walls of the openings to engage the pins. The openings and pins in fact are so proportioned that the unlocking of the other party bars does not take place until the lug 205 on the catch plate 202 corresponding with the operated party bar comes in contact with the arm 209 of the pawl. When a party lever has been fully operated the parts will be in the position shown in Fig. 19, the pin 214 corresponding with the operated party line will be in engagement with the upper wall of the corresponding opening 221. All of the other pins 214 will be in engagement with the lower walls of the corresponding openings 221. The inner arm 81 of the party lever engages a slot 83 in the link the same as in the other form. It will be remembered that stud 215 is riveted to the link and passes through slot 200 in the party bar, the extension and the catch plate, the extension and the catch plate being riveted to the party bar. Should a voter undertake to operate a voting member before pulling the corresponding party lever, the party bar and extension having notches 199 would be carried to the left, the link 226 having incline 222 remaining in the position shown in Fig. 18. The effect would be that notches 199 would engage pawl 208, and thus lock the party bar against other than very slight movement and with it the voting members. This mechanism makes it necessary to either operate the party lever first or else to operate the releasing lever 132 which was fully described in the other form and is not illustrated in the present modification. In Fig. 19, the party lever has been operated and the party bar, the extension, the link and the catch plate have been moved the full distance toward the left. The first effect of this movement is to carry the party bar toward the left far enough to cause the wedge plate 88 to lock the wedge system as in the other form, thus rendering it impossible to operate any other party lever. Simultaneously with this movement pawl 208 commences to ride up the incline 222 on the link to unlock the party line. It

70 75 80 85 90 95 100 105 110 115 120 125 130

should be noted, however, that the wedge system is locked by the movement of wedge plates 88 toward the left before the pawl has traveled up the incline far enough to clear the notches 199. In other words, the other party levers are locked before the operated party lever unlocks the voting members of that party line. The effect is to render it impossible to pull a party lever far enough to unlock the voting members in that line, then operate a voting member and then pull another party lever so as to get the strain of the party lever on the voting member. It will be remembered from the description in the other form that after the wedge system has been locked by a wedge plate 88 it is impossible to withdraw the wedge plate except by means of the resetting lever (not shown in this form) or through the operation of the exit mechanism when the voter leaves the machine. When pawl 208 is in the position shown in Fig. 18, dog 211 is raised out of engagement with projection 223 on the link through the engagement of rounded projection 230 on the dog with correspondingly shaped recess 210 in the pawl. When a party lever is pulled, the corresponding party bar is moved toward the left far enough to carry projection 223 past the dog before the pawl has been raised sufficiently to tilt the dog downward into notch 225 at the end of which is the projection 223. Further travel of the party bar toward the left causes the pawl to be carried to the position shown in Fig. 19 and permits the dog to drop. It will be seen that in this figure the dog is behind the projection. Should scratching occur the party bar will be moved toward the right and the projection will be carried to the position shown in Fig. 20. When this movement takes place dog 211 will ride up over the projection and then drop into the notch in front of the projection. Should the voter attempt to pull the same party lever a second time, the engagement of the dog with the projection will prevent him from doing so and would protect the voting member that has been operated to scratch from the full force of the party lever. When the pawls are returned to their normal position they will raise the dogs again to the position shown in Fig. 18. The operation of special resetting bar 33 is the same as in the other form. This bar is provided with a cam plate 73 co-acting with a lug 74 on a plate 75 riveted to the locking bar as before. The action of counterweight 216 is simply to balance the locking bar and the pawls 208 and retain said bar in its raised or unlocked position when there is scratching.

Second modified form.—This modification shows a different form of locking mechanism adapted to be used where no provision

is made for disconnecting the voting members from the party bars and consequently from the party levers, Fig. 23 showing the parts in the normal or locked position, Fig. 22 the position when a party vote has been cast, and Fig. 21 showing the position of the parts when a split vote has been cast. The parts have been identified by the same numbers as in the principal form so far as practicable and new numbers have been used where there are changes in the construction, all numbers above 233 appearing in this modification only. The links which in the principal form are indicated by 84 and in the first modification by 226 are in this modification indicated by 233. The locking bar which in the principal form is indicated by 84 and in the first modification by 227 is in this modification indicated by 239. The flat studs which in the principal form are indicated by 85 and in the first modification by 215 are in this modification indicated by 247. The operation of the mechanism broadly considered is the same in all three of the forms. When a party lever 76 is pulled the inner arm 81 thereof through its engagement with a slot (not shown) in the corresponding link 233, moves the party bar toward the left from the position shown in Fig. 23 to the position shown in Fig. 21. The corresponding pawl 238 is caused to ride up the incline 249 on the link and to clear the notches 250 in party bar 31 and party bar extension 234 the same as in the other forms. Likewise the corresponding wedge 88 is moved toward the left far enough to lock the wedge system and prevent operation of the other party levers before the party bar and with it the voting members are released by the raising of the pawl above the notches. The link 233, the party bar 31 and the party bar extension 234 are connected together by flat stud 247 as in the first modification and the slot connection of the inner arm 81 of the party lever with the link is the same as in both of the other forms. The party bar extension is provided with downwardly extending lugs 235 and 236 which engage a projection 251 on a lever 237. Lug 235 tilts said lever from the position shown in Fig. 23 to the position shown in Fig. 21. The several levers are pivoted to a connecting strip 243 by means of pins 246, so that the movement of either lever will operate all of the others. When a party lever is operated, the party bar is moved to the left and the projection on the lever is engaged by the right lug and when the parts are returned to their normal position after a voting operation the lever is returned to its normal position by the engagement of the left lug with the projection. The pawls 238 are provided with pins 240 which engage openings 241 in locking bar 239. Levers 237 are pivoted on studs 244

130

and pawls 238 are pivoted on studs 245, both of which are riveted in the framework of the machine. 242 denotes dogs which are pivoted on studs 213 carried by brackets 224 as in the first modification. The dogs are adapted to engage lugs 248 on the links substantially as in the first modification, the left side of said lugs being a vertical wall and the right side an incline by which the 10 dogs are raised when the party bars are moved toward the right and then permitted to drop down in front of the lug after the lug has passed the dog which locks the party bar against being moved toward the 15 left again when there has been scratching as in Fig. 21. It will thus be seen that after a party bar has been moved toward the right in scratching it can only be returned to the voted position by operation of the resetting 20 lever (not illustrated in this form) or by operation of the exit mechanism when the voter leaves the machine. The right end of each dog 242 is shaped to engage with and be operated by the left end of the corresponding 25 pawl 238 substantially as shown in the drawing. It will be noted that the openings 241 in the locking bar are larger than pins 240 on the pawls as in the first modification. It follows therefore as in the 30 first modification that the first portion of the movement of a party bar toward the left by means of the party lever will unlock the voting members of that line through the riding of the corresponding 35 pawl of the incline 249 on the link. Pins 240 in the locked position are in engagement with the upper walls of the opening as in Fig. 23; therefore the other pawls are not raised until the locking bar has moved upward far enough to place the lower walls of the openings in engagement with the pins. In other words, the unlocking of the other 40 party lines does not take place until the last portion of the movement of the party bar 45 toward the left. The locking bar in this form is raised and lowered by means of the levers 237, the connection of the levers to the bar being by means of pins 253. In this form there is no connection between the 50 locking bar and special resetting bar 33, plates 73 and 75 being dispensed with. The connection of bar 33 with the wedge bar being by means of a lip 140 and lug 141 as in the principal form. The oscillation of the 55 levers in raising the locking bar causes the party bars and the extensions to move toward the left. This, however, is not an objection, as it occurs at the last portion of the movement of the party lever. Connecting 60 strip 243 in this form acts as a counter-balance for the locking bar and retains it in the raised position. The resetting in both of the modified forms differs from the principal form in that resetting bar 32 is dispensed with. In the present form, plates

252 are riveted to the right ends of the party bars with which bell crank levers 59 have a stud and slot connection as at 254. These plates take the place of the dogs 57 having shoulders 56 in the principal form, 70 otherwise the operation is the same as before. Operating bar 35 is provided with a cam plate 70 which co-acts with a lug 71 on special resetting bar 33 to return said bar and with it wedge 103 as in the principal 75 form.

The mechanism for preventing a second forward movement of the party levers after a return movement, and comprising the dogs 122 for engaging the notched links 84 and 80 the arms 119 on the catches 109 for operating said dogs, is not broadly claimed herein as it is covered by the claims of my copending application Serial No. 608,383, filed Feb. 13, 1911. Only such features of the 85 form of this mechanism shown and described herein as distinguish the same from the embodiment shown in my said other application are specifically covered by the 90 claims of this case.

Having thus described my invention, I claim:

1. The combination with voting members and a party lever, of a member actuated by the party lever and having an incline, a 95 member actuated by a voting member and having notches and a catch adapted to engage the notches and lock the voting members and to be raised by the incline when the party lever is operated, thereby unlocking 100 the voting members.

2. The combination with voting members and a party lever, of a member actuated by the party lever and having unlocking means, a member actuated by a voting member and having locking means and a catch adapted to engage the locking means to lock the voting members and to be raised by the unlocking means when the party lever is operated, thereby unlocking 105 the voting members.

3. The combination with party levers and voting members, of members having notches, members having inclines, and catches adapted to engage the notches to lock the voting members and to be raised by the inclines to 110 unlock the voting members when a party lever is operated.

4. The combination with party bars having inclines and resetting bars having notches, of catches adapted to engage the notches to lock the resetting bars and to be raised by an incline when a party bar is 115 operated.

5. The combination with voting members, party bars having inclines and resetting bars having notches, of catches adapted to engage the projections to lock the resetting bars and the voting members and to be raised by an incline when a party bar is 120 operated.

6. The combination with party levers and voting members, of party bars having inclines, resetting bars having notches, and catches adapted to engage the notches to lock the resetting bars and the voting members and to be raised by an incline when a party bar is operated. 5
7. The combination with party bars having inclines and resetting bars having notches, of catches adapted to engage the projections to lock the resetting bars and to be raised by the inclines, voting members connected to the resetting bars, party levers connected to the party bars and stud and slot connections between the party bars and the resetting bars. 10
8. The combination with voting members and a party lever, of a member actuated by the party lever and having unlocking means, 20 a member actuated by a voting member and having locking means, a catch adapted to engage the locking means to lock the voting members and to be raised by the unlocking means when the party lever is operated and means for releasing the voting members leaving the party lever locked. 25
9. The combination with party lines of voting members and party levers, of members actuated by the party levers and having unlocking means, members actuated by any voting member in a line and having locking means, catches adapted to engage the locking means to lock the voting members and to be raised respectively by the unlocking means when a party lever is operated to unlock the voting members in that line and means actuated by an operated catch to operate the other catches and release the voting members in the other party 35 lines. 40
10. The combination with party lines of voting members and party levers, of members actuated by the party levers and having inclines, members actuated by any voting member in a line and having notches, catches adapted to engage the notches to lock the voting members and to be raised respectively by an incline when a party lever is operated to unlock the voting members in that line and means actuated by the operated catch to operate the other catches and release the voting members in the other party 45 lines. 50
11. The combination with party lines of voting members and party levers, of members actuated by the party levers and having unlocking means, members actuated by any voting member in a line and having locking means, catches adapted to engage the locking means to lock the voting members and to be raised respectively by the unlocking means when a party lever is operated to unlock the voting members in that line and a locking bar loosely engaged by the catches 55 which is raised by an operated catch to op- 60
- erate the other catches and release the voting members in the other party lines. 65
12. The combination with party lines of voting members and party levers, of members actuated by the party levers and having unlocking means, members actuated by any voting member in a line and having locking means, catches having studs and adapted to engage the locking means to lock the voting members and to be raised respectively by the unlocking means when a party lever is operated to unlock the voting members in that line and a locking bar having notches loosely engaged by the studs of the catches and adapted to be raised by an operated catch to raise the other catches and release the voting members in the other party 70 lines. 75
13. The combination with party lines of voting members and party levers, of members actuated by the party levers and having inclines, members actuated by any voting member in a line and having notches, catches having studs and adapted to engage the notches to lock the voting members and to be raised respectively by an incline when a party lever is operated to unlock the voting members in that party line and a locking bar having notches loosely engaged by the studs of the catches and adapted to be raised by an operated catch to raise the other catches and release the voting members in the other party 80 lines. 85
14. The combination with party lines of voting members and party levers, of members actuated by the party levers and having inclines, members actuated by any voting member in a line and having notches, double catches having cross studs and adapted to engage the notches to lock the voting members and to be raised respectively by an incline when a party lever is operated to unlock the voting members in that party line and a locking bar having angular notches loosely engaged by the cross studs and adapted to be raised by an operated catch to raise the other catches, substantially as shown, for the purpose specified. 90 95
15. The combination with party lines of voting members and party levers, of party bars actuated by the party levers and having inclines, resetting bars connected to the voting members and having notches and catches adapted to engage the notches in the resetting bars to lock the voting members and to be raised respectively by an incline on a party bar when the corresponding party lever is operated to unlock the voting members in that party line. 110 115 120
16. The combination with party lines of voting members and party levers, of party bars actuated by the party levers and having inclines, resetting bars connected to the voting members and having notches, catches adapted to engage the notches in the reset- 125 130

ting bars to lock the voting members and to be raised respectively by an incline on a party bar when the corresponding party lever is operated to unlock the voting members in that party line and means actuated by an operated catch to operate the other catches and unlock the voting members in the other party lines.

17. The combination with party lines of voting members and party levers, of party bars actuated by the party levers and having inclines, resetting bars connected to the voting members and having notches, catches adapted to engage the notches in the resetting bars to lock the voting members and to be raised respectively by an incline on a party bar when the corresponding party lever is operated to unlock the voting members in that party line and a locking bar loosely engaged by the catches which is adapted to be raised by an operated catch to raise the other catches and unlock the voting members in the other party lines.

18. The combination with party lines of voting members and party levers, of party bars actuated by the party levers and having inclines, resetting bars connected to the voting members and having notches, catches having studs and adapted to engage the notches in the resetting bars and to be raised respectively by an incline on the corresponding party bar to unlock the voting members in that party line and a locking bar having angular notches loosely engaged by the studs on the catches whereby said bar is raised by an operated catch and raises the other catches thereby unlocking the voting members in the other party line.

19. The combination with party lines of voting members, party levers, party bars actuated by the party levers and having inclines and resetting bars actuated by the voting members and having plates with projections having notches and inclined arms having offsets, of catches which are adapted to engage the notches to lock the voting members and to be raised respectively by an incline on a party bar when the corresponding party lever is operated and which are provided with arms having offsets adapted to be engaged by the offsets on the inclined arms to complete the movement of an operated catch with a relatively faster travel.

20. The combination with party lines of voting members, party levers, party bars actuated by the party levers and having inclines and resetting bars actuated by the voting members and having plates with projections having notches and inclined arms having offsets, of catches which are adapted to engage the notches to lock the voting members and to be raised respectively by an incline on a party bar when the corresponding party lever is operated and which are provided with arms having offsets adapted to

be engaged by the offsets on the inclined arms to complete the movement of an operated catch with a relatively faster travel and a locking bar loosely engaged by the catches which operates when raised by a catch to raise the other catches and unlock the voting members in the other party lines.

21. The combination with voting members and a party lever, of a resetting bar to which the voting members are connected, a party bar and a link which is adapted to be operated by the party lever, is positively connected to the party bar and is loosely connected to the resetting bar.

22. The combination with voting members and a party lever, of a party bar, a link which is engaged by the party lever, a stud connecting the link and the party bar and a resetting bar to which the voting members are connected and which is provided with an elongated slot through which the stud passes.

23. The combination with voting members and a party lever, of a party bar, a link actuated by the party lever, a stud connecting the link and the party bar, and a resetting bar having pin and slot connections with the voting members.

24. The combination with voting members and a party lever, of a party bar, a link actuated by the party lever, a stud connecting the link and the party bar and a resetting bar having an elongated slot through which the stud passes.

25. The combination with voting members and a party lever, of a party bar, a link actuated by the party lever, a stud connecting the link and the party bar, a resetting bar having an elongated slot through which the stud passes and pin and slot connections between the voting members and the party and resetting bars.

26. The combination with voting members, party levers and party and resetting bars having pin and slot connections with the voting members, of links and studs connecting said links with the party bars, the resetting bars being provided with elongated slots through which the studs pass, so that when a party lever is operated movement will first be imparted to the party bar and then to both bars in unison.

27. The combination with party lines of voting members, party levers, resetting bars having locking means, party bars having unlocking means and connections between the voting members and the party and resetting bars, of links, studs connecting said links with the party bars and catches adapted to engage the locking means to lock the voting members and to be raised by the unlocking means, the resetting bars being provided with elongated slots through which the studs pass, so that when a party lever is operated movement will first be imparted to the party bar to unlock the corresponding

- line of voting members and then the party and resetting bars will move in unison.
28. The combination with party lines of voting members, party levers, resetting bars having notches, party bars having inclines and pin and slot connections between the voting members and the party and resetting bars, of links, studs connecting said links with the party bars and catches adapted to engage the notches to lock the resetting bars and the voting members and to be raised by the inclines to unlock the voting members, the resetting bars being provided with elongated slots engaged by the studs, so that when a party lever is operated movement will first be imparted to the party bar to unlock the corresponding line of voting members and then the party and resetting bars will move in unison.
29. The combination with party lines of voting members, party levers, resetting bars having locking means, party bars having unlocking means and connections between the voting members and the party and resetting bars, of links, studs connecting said links with the party bars and catches adapted to engage the locking means to lock the voting members and to be raised by the unlocking means, the resetting bars being provided with elongated slots through which the studs pass, and means actuated by an operated catch to operate the other catches and release the voting members in the other party lines.
30. The combination with party lines of voting members, party levers, resetting bars having locking means, party bars having unlocking means and connections between the voting members and the party and resetting bars, of links, studs connecting said links with the party bars and catches adapted to engage the locking means to lock the voting members and to be raised by the unlocking means, the resetting bars being provided with elongated slots through which the studs pass, and a locking bar loosely engaged by the catches and which is raised by an operated catch to operate the other catches and release the voting members in the other party lines.
31. The combination with party lines of voting members, party levers, resetting bars having notches, party bars having inclines and pin and slot connections between the voting members and the party and resetting bars, of links, studs connecting said links with the party bars and catches adapted to engage the notches to lock the resetting bars and the voting members and to be raised by the inclines to unlock the voting members, the resetting bars being provided with elongated slots engaged by the studs, for the purpose set forth, and the catches being provided with studs, and a locking bar having angular notches loosely engaged by the studs of the catches and adapted to be raised by an operated catch to raise the other catches and release the voting members in the other party lines.
32. The combination with party lines of voting members, party levers, resetting bars having plates with projections provided with notches and inclined arms having offsets, party bars having inclines and connections between the voting members and the party and resetting bars, of links engaged by the party levers, studs connecting said links with the party bars, said resetting bars being provided with elongated slots through which the studs pass and catches adapted to engage the notches and to be raised by an incline when the corresponding party lever is operated and which are provided with arms having offsets adapted to be engaged by the offsets on the inclined arms to complete the movement of an operated catch with a relatively faster travel.
33. The combination with party lines of voting members, party levers, resetting bars having plates with projections provided with notches and inclined arms having offsets, party bars having inclines and connections between the voting members and the party and resetting bars, of links engaged by the party levers, studs connecting said links with the party bars, said resetting bars being provided with elongated slots through which the studs pass, catches adapted to engage the notches and to be raised by an incline when the corresponding party lever is operated and which are provided with arms having offsets adapted to be engaged by the offsets on the inclined arms to complete the movement of an operated catch with a relatively faster travel, and a locking bar loosely engaged by the catches and which is raised by an operated catch to operate the other catches and release the voting members in the other party lines.
34. The combination with voting members, party levers, party bars having unlocking means, links engaged by the party levers and having notches, studs connecting the links and the party bars, and resetting bars having locking means and elongated slots through which the studs pass, of catches adapted to engage the locking means and to be raised by the unlocking means and provided with arms having hooks, and dogs having slots engaged by the hooks and adapted to engage the notches in the resetting bars to lock said bars against a second forward movement after a return movement.
35. The combination with voting members, party levers, party bars having unlocking means, links engaged by the party levers and having notches, studs connecting the links and the party bars, and resetting bars having locking means and elongated slots through which the studs pass, of

- catches adapted to engage the locking means and to be raised by the unlocking means and provided with arms and dogs engaged by the arms of the catches and adapted to engage the notches in the resetting bars to lock said bars against a second forward movement after a return movement. 70
36. The combination with party bars, party levers and links connected to the party bars and actuated by the party levers and provided with T-shaped lugs, of wedge plates having correspondingly shaped recesses with necks of greater width than the necks of the lugs to permit vertical movement of said wedge plates, and wedge plates intermediate the connected wedge plates, the wedge plates above an operated wedge plate being raised by operation of a party lever and locking the other party levers against 75 operation. 80
37. The combination with party bars, party levers and links connected to the party bars and actuated by the party levers, of wedge plates loosely connected to the links 25 and having vertical movement independently of the links, wedge plates intermediate the connected wedge plates and a fixed wedge plate at the top of the wedge system, substantially as described, for the purpose 85 specified. 90
38. The combination with party bars, party levers and links connected to the party bars and actuated by the party levers, of wedge plates loosely connected to the links 35 each wedge plate being provided on its upper and lower sides and at its forward and rear ends with spaced inclines, and wedge plates intermediate the connected wedge plates which are provided with correspond- 95 ing inclines. 100
39. The combination with party bars, party levers and links connected to the party bars and actuated by the party levers, of wedge plates loosely connected to the links, 45 wedge plates intermediate the connected wedge plates which are provided with recesses, and blocks in said recesses which retain said plates against other than vertical movement. 110
40. The combination with voting members, party bars, a releasing bar and party levers, of means operated by the party levers for locking all other party levers and unlocking the corresponding voting members when a party lever is operated and means operated by the releasing bar for locking all the party levers leaving all the voting members unlocked. 115
41. The combination with voting members, party levers, members actuated by the party levers and having unlocking means and members connected with the voting members and having locking means, of catches adapted to engage the locking means 55 to lock the voting members and to be raised 120 by the unlocking means when a party lever is operated, a locking bar connected to the catches whereby said catches may be raised to unlock the voting members, a releasing shaft connected with the locking bar and means actuated by the releasing shaft for locking the party levers. 125
42. The combination with voting members, party levers and connections between the party levers and the voting members, of catches adapted to lock the voting members, a locking bar by which the catches are raised to unlock the voting members and a releasing shaft connected with the locking bar for locking the party levers. 75
43. The combination with voting members, party levers and connections between the party levers and the voting members, of catches adapted to lock the voting members, a locking bar by which the catches are raised to unlock the voting members, superposed wedge plates, a releasing shaft and a wedge bar connected with said shaft by which the wedge plates are actuated to lock the party levers. 85
44. The combination with voting members, party levers and connections between the party levers and the voting members, of catches adapted to lock the voting members, a locking bar by which the catches are raised to unlock the voting members, superposed wedge plates, a wedge bar, a releasing shaft and a bell crank lever carried by said shaft and connected to the locking bar and the wedge plates. 90
45. The combination with voting members, party levers and connections between the party levers and the voting members, of catches adapted to lock the voting members, a locking bar by which the catches are raised to unlock the voting members, superposed wedge plates, a wedge bar, a releasing shaft and a bell crank lever carried by said shaft and loosely connected to the locking bar and the wedge bars, leaving said bars free to be moved in one direction independently of the releasing shaft. 100
46. The combination with voting members, party levers and connections between the party levers and the voting members, of catches adapted to lock the voting members, a locking bar by which the catches are raised to unlock the voting members, superposed wedge plates, a wedge bar, a releasing shaft, a bell crank lever carried by said shaft and pin and slot connections between said lever and said bars, substantially as described, for the purpose specified. 110
47. The combination with voting members, party levers, independent voting mechanism and connections between the party levers and the voting members, of catches adapted to lock the voting members, a locking bar by which the catches are raised to unlock the voting members, connections be- 120 130

- tween said bar and the independent voting mechanism and means for locking the other party levers when a party lever is operated.
48. The combination with voting members, party levers, independent voting mechanism and connections between the party levers and the voting members, of catches adapted to lock the voting members, a locking bar by which the catches are raised to unlock the voting members, connections between said bar and the independent voting mechanism and means for locking the party levers leaving the voting members and the independent voting mechanism unlocked. 15
49. The combination with voting members, party levers, interlocking members engaged by the voting members and connections between the party levers and the voting members, of catches adapted to lock the voting members, a locking bar by which the catches are raised to unlock the voting members and means for locking the party levers. 20
50. The combination with voting members, party levers, interlocking members engaged by the voting members and connections between the party levers and the voting members, of catches adapted to lock the voting members, a locking bar by which the catches are raised to unlock the voting members, a releasing shaft connected with the locking bar, means operated by the party levers to lock the other party levers and means operated by the releasing shaft to lock all the party levers. 25
51. The combination with party lines of voting members, party levers, members actuated by the party levers and having unlocking means, members actuated by a voting member and having locking means, and catches adapted to engage the locking means to lock the voting members and to be raised by the unlocking means when a party lever is operated, of a locking bar engaged by the catches which when raised by an operated catch raises the other catches and unlocks the other party lines, a releasing shaft connected with the locking bar and means operated by said shaft for locking the party levers. 40
52. The combination with party lines of voting members, party levers, members actuated by the party levers and having unlocking means, members actuated by a voting member and having locking means, and catches adapted to engage the locking means to lock the voting members and to be raised by the unlocking means when a party lever is operated, of a locking bar engaged by the catches which when raised by an operated catch raises the other catches and unlocks the other party lines, superposed wedges, connections between said wedges and the party levers by which the other party levers are 45
- locked when a party lever is operated, a releasing shaft connected with the locking bar and connections between said shaft and the wedge system by which all party levers are locked, leaving the voting members unlocked. 70
53. The combination with voting members, party bars connected therewith, party levers connected with the party bars and means for resetting said voting members and party levers after the voting operation, of a resetting shaft, an operating bar connected therewith and connections between said bar and the party bars, actuation of the resetting shaft acting independently of said first named resetting means to reset an operated party lever and all operated voting members. 75
54. The combination with voting members, party bars connected therewith, party levers connected with the party bars, resetting bars connected with the voting members, and means for resetting said voting members and party levers after the voting operation, of an auxiliary resetting shaft, an operating bar connected therewith and connections between said bar and the party and resetting bars. 80
55. The combination with voting members, party bars connected therewith and having dogs and party levers connected with the party bars, of a resetting shaft, an operating bar connected therewith and bell crank levers connected with the operating bar and engaging the dogs, substantially as 85 described, for the purpose specified. 90
56. The combination with voting members, party bars connected therewith, party levers connected with the party bars and resetting bars connected with the voting members, of a resetting shaft, an operating bar connected therewith and bell crank levers connected with the operating bar and engaging the party and resetting bars. 105
57. The combination with voting members, party bars connected therewith and having dogs, party levers connected with the party bars and resetting bars connected with the voting members and having dogs, of a resetting shaft, an operating bar connected therewith and a bell crank lever connected with the operating bar and having a cross pin adapted to engage the dogs. 110
58. The combination with voting members, party bars connected therewith, party levers connected with the party bars and resetting bars connected with the voting members, of a resetting shaft, an operating bar connected therewith and bell crank levers adapted to engage the party and resetting bars for the purpose set forth and having pin and slot connections with the operating bar to permit movement of said levers independently of the bar. 120
59. The combination with voting mem- 130

- bers, party bars connected therewith and party levers connected with the party bars, of a resetting shaft, an operating bar connected therewith, bell crank levers having 5 pin and slot connections with the operating bar and adapted to engage the party bars, a cam bar and connections between said bar and the party bars, actuation of the resetting shaft acting to reset the party levers 10 and voting members independently of the cam bar.
60. The combination with voting members, party bars connected therewith and party levers connected with the party bars, 15 of a resetting shaft, an operating bar connected therewith, connections between said bar and the party bars, a cam bar and connections between said bar and the party and resetting bars.
61. The combination with voting members, party bars connected therewith, party levers connected with the party bars and resetting bars connected with the voting members, of a resetting shaft, an operating bar 20 connected therewith, bell crank levers loosely connected with the operating bar and adapted to engage the party and resetting bars, a cam bar and links loosely connecting the cam bar with the party and resetting bars.
62. The combination with voting members, party levers and party bars and resetting bars, of a cam bar having inclined slots, links having pins engaging said slots and 25 having pin and slot connections with the party and resetting bars, a resetting shaft, an operating bar connected therewith, and bell crank levers adapted to engage the party and resetting bars and having pin and slot connections with the operating bar, so 30 that the voting members and party levers may be reset independently of the cam bar.
63. The combination with voting members, party levers and party bars, of a cam 45 bar having inclined slots, links having pins engaging said slots and having pin and slot connections with the party bars, a resetting shaft, an operating bar connected therewith and bell crank levers adapted to 50 engage the party bars and loosely connected with the operating bar.
64. The combination with voting members, party levers and party bars, of a cam bar, operating connections between the cam 55 bar and the party bars which leave the party bars free to be reset independently of the cam bar, a resetting shaft, an operating bar connected therewith and bell crank levers adapted to engage the party bars and 60 loosely connected with the operating bar.
65. The combination with voting members, party levers and party bars having dogs, of a cam bar having inclined slots, links having pins engaging said slots and 65 loosely connected with the party bars, a re-
- setting shaft, an operating bar connected therewith and bell crank levers adapted to engage the dogs and having pin and slot connections with the operating bar.
66. The combination with voting members, party levers, and party bars and resetting bars having dogs, of a cam bar having inclined slots, links having pins engaging said slots and pin and slot connections with the party and resetting bars, a resetting shaft, an operating bar connected therewith and bell crank levers adapted to engage the party and resetting bars and loosely connected with the operating bar.
67. The combination with party bars having dogs with shoulders and a cam bar, of links loosely connecting the party bars and the cam bar and latches having operating connection with the cam bar and adapted to engage the shoulders to lock the party bars 85 until the cam bar is raised.
68. The combination with party bars having dogs with shoulders and arms, a cam bar, links loosely connecting the party bars and the cam bar and actuated by the cam bar and latches having operating connection with the cam bar and adapted to engage the shoulders for the purpose set forth, of a releasing shaft, an operating bar connected therewith and bell crank levers adapted to 90 engage the arms and loosely connected with the locking bar.
69. The combination with party and resetting bars having dogs with shoulders and arms, a cam bar, links loosely connecting the party and resetting bars and the cam bar and actuated by the cam bar and latches having operating connection with the cam bar and adapted to engage the shoulders, of a releasing shaft, an operating bar connected 95 therewith and bell crank levers adapted to engage the arms and having pin and slot connections with the locking bar.
70. The combination with party lines of voting members, party levers, members actuated by the party levers and having unlocking means, members actuated by a voting member and having locking means and catches adapted to engage the locking means and to be raised by the unlocking means 100 when a party lever is operated to unlock a party line, of a locking bar loosely engaging said catches and acting to unlock the other party lines, a system of superposed wedge plates actuated by a party lever to lock the other party levers, a resetting shaft, an operating bar connected therewith, connections between said bar and the members actuated by the party levers and voting members, a special resetting bar and connections between said bar and the locking and operating bars, so that operation of the resetting shaft will reset the party levers and voting members, unlock the wedge system and return the locking bar.

71. The combination with voting members, party levers, party bars having locking means, resetting bars having unlocking means and catches adapted to engage said locking means and be raised by the unlocking means when a party lever is operated, of a system of superposed wedge plates for locking the party bars, a wedge bar co-acting with the wedge system, a resetting shaft, an operating bar connected therewith, connections between said bar and the party and resetting bars, a special resetting bar engaging the wedge bar and operating connections between the operating bar and the special resetting bar. 70
72. The combination with party levers, party bars and a system of superposed wedge plates for locking the party bars, of a wedge bar co-acting with the wedge plates, a resetting shaft, an operating bar connected therewith, connections between said bar and the party bars, a special resetting bar engaging the wedge bar and operating connections between the operating bar and the special resetting bar. 75
73. The combination with party levers, party bars and a system of superposed wedge plates for locking the party bars, of a wedge bar co-acting with the wedge plates and having a lug, a resetting shaft, an operating bar connected therewith and having a cam plate, connections between said bar and the party bars, a special resetting bar having a lip engaging the lug on the wedge bar and a cam plate with a lug adapted to be engaged by the cam plate on the operating bar. 80
74. The combination with voting members, party levers, party bars, a system of superposed wedge plates, links loosely connecting the party bars with wedge plates and a wedge bar co-acting with the wedge plates, of a releasing shaft, a connection between said shaft and the wedge bar, a resetting shaft, an operating bar connected therewith, connections between said bar and the party bars, a special resetting bar engaging the wedge bar and connections between the operating bar and the special resetting bar. 85
75. The combination with voting members, party levers, party and resetting bars and catches co-acting with said bars, of a system of superposed wedge plates, links loosely connecting the party bars with wedge plates and a wedge bar co-acting with the wedge plates, of means for actuating the wedge bar to lock the party levers, means for unlocking the voting members and means for resetting operated voting members. 90
76. The combination with voting members, party levers, party and resetting bars and catches co-acting with said bars, of a locking bar loosely connected to the catches for the purpose set forth, a special reset- 95
- ting bar adapted to engage the locking bar, an operating bar adapted to engage the special resetting bar and connections between the operating bar and the party and resetting bars. 100
77. The combination with voting members, party levers and party bars, of superposed wedge plates, links connecting the party bars with wedge plates, a wedge bar co-acting with the wedge plates, operation of a party lever acting to lock the other party levers and operation of a wedge plate acting to lock all party levers and a resetting bar and connections acting to return operated party levers and voting members 105
78. The combination with voting members, party levers and party bars, of superposed wedge plates, a wedge bar co-acting therewith, means for locking the voting members, a locking bar co-acting therewith, a releasing shaft and a bell crank lever carried thereby and having pin and slot connections with the locking bar and the wedge plates. 110
79. The combination with voting members, party levers and party bars, of superposed wedge plates, a wedge bar co-acting therewith, means for locking the voting members, a locking bar co-acting therewith, a releasing shaft and connections with the wedge bar and locking bar, and a resetting shaft and connections with the wedge bar and the party bars. 115
80. The combination with voting members, party bars and party levers, of locking means for the voting members, locking means for the party levers and a releasing shaft and connections by which the voting members are released and the party levers 120
- are locked. 125
81. The combination with voting members, party bars and party levers, of locking means for the voting members, a cam bar having pin and slot connections with the party bars, a resetting shaft and connections intermediate said shaft and the party bars acting to reset the voting members and party bars independently of the cam bar. 130
82. The combination with oscillatory voting members having arms and a lug between said arms and party and resetting bars lying on opposite sides of said lug, of pins having heads inclosing the voting members and adapted to slide thereon and to engage the lug and one or both of the arms to permanently connect the resetting bars with the voting members and to detachably connect the party bars with the voting members. 135
83. The combination with oscillatory voting members having arms and a lug between said arms and party and resetting bars lying on opposite sides of said lug, of pins having heads inclosing the voting members and 140

adapted to slide thereon and to engage the lug and one or both of the arms to permanently connect the resetting bars with the voting members and to detachably connect 5 the party bars with the voting members and means for locking the pins in either of their operative positions.

84. The combination with oscillatory voting members having arms and a lug between 10 said arms and party and resetting bars lying on opposite sides of said lug and provided with elongated slots, of pins having heads inclosing the voting members and adapted to slide thereon and pass through the slots 15 in the bars and to engage the lug and one or both of the arms to permanently connect the resetting bars and to detachably connect the party bars with the voting members.

85. The combination with oscillatory voting 20 members and party and resetting bars, of means for permanently connecting the resetting bars and for detachably connecting the party bars with the voting members.

86. The combination with oscillatory voting 25 members and party and resetting bars having elongated slots, of pins which slide on the voting members and engage the slots in the resetting bars to permanently connect said bars with the voting members and are 30 adapted to engage the slots in the party bars to detachably connect said bars with the voting members.

87. The combination with oscillatory voting 35 members and party and resetting bars, of pins for permanently connecting the resetting bars and for detachably connecting the party bars with the voting members, and means for locking the pins in either of their engaging positions.

88. The combination with oscillatory voting 40 members and party and resetting bars having elongated slots, of pins which slide on the voting members and engage the slots in the resetting bars to permanently connect said bars with the voting members and are 45 adapted to engage the slots in the party bars to detachably connect said bars with the voting members and means for locking the pins in either of their engaging positions.

89. The combination with oscillatory voting 50 members having arms and a lug between said arms and party and resetting bars having elongated slots and lying between said lugs and the arms, of pins having heads 55 which engage the voting members leaving the pins free to slide and which are adapted to pass through the slots in the bar and to engage the lug and one or both of the arms.

90. The combination with oscillatory voting 60 members having arms and a lug between said arms and party and resetting bars having elongated slots, of sliding pins adapted to engage the slots in the bars and the lugs and arms of the voting members and having

heads inclosing the voting members and 65 locking slides adapted to engage the heads of the pins to lock said pins in engagement with the lugs and with one or both of the arms.

91. The combination with oscillatory voting 70 members having arms and a lug between said arms and party and resetting bars having elongated slots, of sliding pins adapted to engage the slots in the bars and the lugs and arms of the voting members and having 75 heads inclosing the voting members, locking slides having flanges adapted to engage the heads of the pins and recesses which permit the flanges to move out of alinement with the heads of the pins, and latches for retaining 80 said slides in the locking position.

92. The combination with voting members in office columns and interlocking members corresponding to said office columns, of a restricting bar and restricting members operated thereby and arranged respectively to engage and operate the several interlocking 85 members to render predetermined voting members inoperative.

93. The combination with voting members, interlocking members and party levers, of a system of superposed wedge plates acting to lock the party levers, restricting mechanism and connections intermediate the restricting mechanism and the interlocking 95 members and wedge system.

94. The combination with voting members, party bars, party levers, and interlocking members, of a system of superposed wedge plates, connections between the party 100 bars and wedge plates, restricting mechanism and connections between said mechanism and the interlocking members and wedge system.

95. The combination with voting members 105 and interlocking members for locking said voting members, of restricting members for operating said interlocking members, a restricting bar for operating said restricting members, and means for detachably connecting said restricting members and bar.

96. The combination with lines of voting members and interlocking members, of restricting members lying below the voting members, dogs operated by the restricting 115 members and engaging the voting members in the lower line and a restricting bar to which the restricting members are detachably connected.

97. The combination with lines of voting 120 members and interlocking members comprising cam plates, side plates and stud and slot connections between said plates acting to shorten the member when a cam plate is moved laterally, of restricting members lying below the voting members and acting upon the same cam plates as the lower line of voting members, dogs operated by the

- restricting members and engaging the lower line of voting members and a restricting bar to which the restricting members are detachably connected.
98. The combination with voting members and interlocking members comprising cam plates and side plates and stud and slot connections between said plates, of oscillatory restricting members having lugs adapted to engage cam plates, a restricting bar and pin and slot connections between the restricting members and the restricting bar.
99. The combination with voting members and interlocking members comprising cam plates and side plates and stud and slot connections between said plates, of oscillatory restricting members having lugs adapted to engage cam plates and arms, dogs pivoted to said arms and adapted to engage the voting members in the lower line, a restricting bar and pin and slot connections between the restricting members and the restricting bar.
100. The combination with voting members and interlocking members, of restricting members comprising oscillatory shafts and arms, a restricting bar and pin and slot connections between the arms and the restricting bar.
101. The combination with framework having holes and oscillatory restricting members journaled in the framework and having arms, of a restricting bar having slots and pins adapted to engage either the holes in the framework to lock the restricting members out of operation or the slots in the restricting bar to connect the restricting members therewith.
102. The combination with voting members and interlocking members, of restricting members comprising oscillatory shafts and arms, a restricting bar, pin and slot connections between the arms and the restricting bar and swinging latches for locking the pins in place.
103. The combination with framework having holes and oscillatory restricting members journaled in the framework and having arms, of a restricting bar having slots, pins adapted to engage either the holes in the framework to lock the restricting members out of operation or the slots in a restricting bar to connect the restricting members therewith and swinging latches for locking the pins in either of their engaging positions.
104. The combination with voting members in office columns and interlocking members, of oscillatory restricting members corresponding with the office columns, a restricting bar, detachable connections between the restricting members and the bar and means for locking the restricting members in engagement with the bar.
105. The combination with voting mem-
- bers in office columns and oscillatory restricting members corresponding with the office columns, of a reciprocatory restricting bar and means for detachably connecting the restricting members with the bar.
106. The combination with framework, voting mechanism and oscillatory restricting members, of a reciprocatory restricting bar and means for detachably connecting the restricting members with either the framework or the restricting bar.
107. The combination with voting mechanism and interlocking members, of a restricting bar, means for detachably connecting the restricting members to the bar, a restricting shaft having an arm and a link connecting the restricting bar with said arm.
108. The combination with an oscillatory restricting shaft having arms, a restricting bar, a system of superposed wedge plates and a wedge bar adapted to actuate the wedge plates, for the purpose set forth, of a link connecting the restricting bar with one of the arms on the restricting shaft and pivoted links connected respectively to the wedge bar and to the other arm on the restricting shaft.
109. The combination with an oscillatory restricting shaft, an oscillatory releasing shaft, a locking bar and a system of superposed wedge plates, of voting members, locking means therefor controlled by the locking bar, party levers adapted to be locked by the wedge system, a wedge bar, a restricting bar and connections between the restricting shaft and the restricting bar and wedge bar and between the releasing shaft and the locking bar and wedge bar.
110. The combination with party lines of voting members, and party levers by which the voting members in a line are operated simultaneously, of interlocking members which when a voting member is operated lock the other voting members in that office column, a system of superposed wedge plates which lock all other party levers when a party lever is operated and releasing mechanism acting to lock all party levers leaving all voting members unlocked.
111. The combination with voting members, party levers and interlocking members, of a system of superposed wedge plates and restricting mechanism acting in connection with the wedge system to lock the party levers and in connection with the voting members and interlocking members to lock predetermined voting members against operation.
112. The combination with voting members in party lines and office columns, party levers corresponding to said party lines, and interlocking members corresponding to said office columns, of restricting members arranged respectively to engage and operate

the several interlocking members, a restricting bar for operating said restricting members, and intermediate connections between said restricting bar and party levers.

5 113. The combination with voting members, party levers, interlocking members and a system of superposed wedge plates, of restricting members, a restricting bar to which they are detachably connected, a restricting 10 shaft and connections between said shaft and the restricting bar and the wedge system.

114. The combination with voting members, party levers, interlocking members and 15 a system of superposed wedge plates, of restricting members, a restricting bar to which they are detachably connected, a restricting shaft to which said bar is connected, a wedge 20 bar and connections between the restricting shaft and the wedge bar.

115. The combination with voting mechanism, interlocking mechanism, restricting mechanism and a system of superposed wedge plates, of a locking bar, a wedge bar, 25 a releasing shaft and connections for operating the locking bar and the wedge plate, and a restricting shaft and connections for operating the wedge bar, the locking bar and the restricting mechanism.

30 116. The combination with voting mechanism, interlocking mechanism, a restricting bar, restricting members detachably connected thereto and a system of superposed wedge plates, of a locking bar, a wedge bar, 35 a releasing shaft, a bell crank lever carried thereby and loosely connected to the locking bar and the wedge bar, a restricting shaft having arms one of which is loosely connected to the wedge bar and links pivoted 40 to each other and pivoted respectively to the other arm on the restricting shaft and to the arm of the bell crank lever that is connected to the wedge bar.

117. The combination with voting members, party levers and means for locking 45 said members and levers, of a wedge bar, a locking bar, a bell crank lever loosely connected to said bars, a special resetting bar having a lip engaging the wedge bar, a link 50 pivoted to the bell crank lever and having a lug engaging the lip on the special resetting bar, a restricting bar, a restricting shaft having arms, a link connecting the restricting bar to one of said arms and a link connecting the link having the lug to the other 55 arm.

118. The combination with voting mechanism, means for locking said mechanism, a wedge bar and a locking bar, of a bell crank 60 lever having pin and slot connections with said bars, a special resetting bar engaging the wedge bar, a link pivoted to the bell crank lever and having a lug engaging the special resetting bar, a restricting bar, a re-

stricting shaft having arms, a link connecting the restricting bar to one of said arms and a link connecting the link having the lug to the other arm. 65

119. The combination with voting mechanism, means for locking said mechanism, a wedge bar and a locking bar, of a bell crank lever having pin and slot connections with said bars, a restricting bar, restricting members detachably connected to said bar, a special resetting bar engaging the wedge 75 bar, a link pivoted to the bell crank lever and having a lug engaging the special resetting bar, a restricting shaft having arms, a link connecting the restricting bar to one of said arms and a link connecting the link having the lug to the other arm. 80

120. The combination with voting members, party bars having unlocking means, resetting bars having locking means, catches adapted to engage the locking means and to 85 be raised by the unlocking means, party levers and a system of superposed wedge plates, of a wedge bar, a restricting bar, a special resetting bar engaging the wedge bar, a locking bar loosely connected to the 90 catches, a bell crank lever loosely connected to the wedge bar and the locking bar, a link pivoted to the bell crank lever and having a lug engaging the special resetting bar, a restricting shaft having arms, a link connect- 95 ing the restricting bar to one of said arms and a link connecting the link having the lug to the other arm.

121. The combination with voting mechanism, locking mechanism therefor and restricting mechanism, of a locking bar, a special resetting bar therefor, a wedge bar engaging the special resetting bar, a bell crank lever loosely connected to the wedge bar and to the locking bar, a restricting 100 shaft having arms, a link connecting one of said arms with the restricting mechanism, and links pivoted to each other one of which is pivoted to the other arm on the restricting 105 shaft, the other of said links being pivoted to the bell crank lever and having a lug engaging the special resetting bar. 110

122. The combination with voting mechanism, locking mechanism therefor, restricting mechanism, a releasing shaft and a bell 115 crank lever carried thereby, of a locking bar, a wedge bar, pin and slot connections between the bell crank lever and the locking bar and wedge bar, a special resetting bar engaging the wedge bar, a restricting shaft 120 having arms, a link connecting one of said arms with the restricting mechanism, and links pivoted to each other one of which is pivoted to the other arm on the restricting shaft the other link being pivoted to the bell 125 crank lever and having a lug engaging the special resetting bar.

123. The combination with voting mecha-

nism, locking mechanism therefor, restricting mechanism, a releasing shaft and a bell crank lever carried thereby, of a locking bar, a wedge bar having a lug, pin and slot connections between the bell crank lever and the locking bar and wedge bar, a special resetting bar having a lip engaging the lug on the wedge bar, a restricting shaft having arms, a link connecting one of said arms with the restricting mechanism, and links pivoted to each other one of which is pivoted to the other arm on the restricting shaft, the other link being pivoted to the bell crank lever and having a lug engaging the lip on the special resetting bar.

124. The combination with voting mechanism, locking mechanism therefor and restricting mechanism, of a special resetting bar, connections between said bar and the restricting and voting mechanisms, an operating bar, connections between said bar and the special resetting bar and a resetting shaft and connections with the operating bar.

125. The combination with voting mechanism, locking mechanism therefor and restricting mechanism, of a special resetting bar, connections between said bar and the restricting and voting mechanisms, an operating bar, connections between said bar and the special resetting bar, a cam bar and connections between the cam bar and the special resetting bar and the operating bar.

126. The combination with party and resetting bars having elongated slots and oscillatory voting members having pins engaging said slots, of a cam bar, loose connections between the cam bar and the party and resetting bars, a resetting shaft, an operating bar and connections between the operating bar and the resetting shaft and between said bar and the party and resetting bars.

127. The combination with voting members, party levers for actuating the voting members and a cam bar and connections for locking and unlocking the party levers, of mechanism for locking the other party levers when a party lever is actuated, interlocking members, for the purpose set forth, and resetting mechanism for returning all actuated party levers and voting members to the non-voting position without actuating the cam bar.

128. The combination with voting members, party levers for actuating the voting members and a cam bar and connections for locking and unlocking the party levers, of a system of superposed wedge plates for locking the other party levers when a party lever is actuated, interlocking members and resetting mechanism and connections for unlocking the wedge system and returning operated party levers and voting members to the non-voting position without operating the cam bar.

129. The combination with voting members, party levers for actuating the voting members and a cam bar and connections for locking and unlocking the party levers, of interlocking members, releasing mechanism and connections for locking the party levers and releasing the voting members and resetting mechanism for returning operated party levers and voting members to the non-voting position.

130. The combination with voting members and party levers, of party bars operated by said party levers and having openings therein, and sliding pins carried by said voting members and movable thereon into and out of engagement with the openings in said party bars.

131. The combination with voting members, party levers for actuating the voting members and a cam bar and connections for locking and unlocking the party levers, of interlocking members and a restricting shaft, a restricting bar and restricting members co-acting with the interlocking members.

132. The combination with voting members in office columns and party levers for actuating the voting members, of interlocking members, party bars, restricting members corresponding with the office columns and co-acting with the interlocking members and a restricting bar to which the restricting members are detachably connected.

133. The combination with party lines of voting members and party levers, of party bars, resetting bars and sliding pins on the voting members which permanently engage the resetting bars and detachably engage the party bars.

134. The combination with party lines of voting members and party levers, of party bars, resetting bars and means for connecting the voting members with the resetting bars and for detachably connecting said members with the party bars.

135. The combination with party lines of voting members and party levers, of party bars and resetting bars having slots and sliding pins on the voting members engaging said slots to permanently connect the resetting bars and detachably connect the party bars with the voting members.

136. The combination with party lines of voting members and party levers, of party bars, resetting bars, sliding pins on the voting members which permanently engage the resetting bars and are adapted to detachably engage the party bars, and means for locking said pins in either of their engaging positions.

137. The combination with voting members, party bars having inclines and resetting bars having notches, of catches adapted to engage the notches and to be raised by

the inclines, a locking bar loosely connected with the catches and means controlled by the resetting bars for raising the locking bar.

138. The combination with voting members, party bars, resetting bars and catches which engage the resetting bars and are raised by the party bars, of latches for locking the party and resetting bars, a cam bar and links controlled by the cam bar for 10 raising the latches and releasing the party and resetting bars.

139. The combination with voting members, party bars, resetting bars and catches which engage the resetting bars and are 15 raised by the party bars, of an operating bar and connections with the party and resetting bars, a locking bar loosely connected with the catches and a special resetting bar for returning the operating and locking bars to 20 their normal position.

140. The combination with voting members, party levers, members actuated by the party levers and having unlocking means and members actuated by voting members 25 and having locking means, of catches adapted to engage the locking means and to be raised by the unlocking means and a cam bar and connections for unlocking the members and for returning said members and operating voting members and party levers to 30 their normal position and locking them.

141. The combination with voting members, party levers, members actuated by the party levers and having unlocking means 35 and members actuated by voting members and having locking means, of catches adapted to engage the locking means and to be raised by the unlocking means, a system of superposed wedge plates acting to lock the 40 other party levers when a party lever is operated, a special resetting bar and connections with the wedge system and a cam bar and connections with the members and special resetting bar for returning operated voting 45 members and party levers to their normal position and releasing the wedge system.

142. The combination with voting members, party levers, party and resetting bars and a system of superposed wedge plates, of 50 a special resetting bar and connections with the wedge system, and a cam bar and connections with the party, resetting and special resetting bars.

143. The combination with voting members, party levers, party bars having unlocking means, resetting bars having locking means and catches adapted to engage the locking means and to be raised by the unlocking means, of a system of superposed 55 wedge plates acting to lock the party levers, a locking bar loosely connected with the catches and a special resetting bar co-acting with the locking bar and the wedge system.

144. The combination with voting mem-

bers, party levers, party bars having unlocking means, resetting bars having locking means and catches adapted to engage the locking means and to be raised by the unlocking means, of a locking bar loosely connected with the catches, an operating bar, 70 a resetting shaft by which said bar is actuated and a special resetting bar co-acting with the locking and operating bars.

145. The combination with voting members, party levers, party bars having unlocking means, resetting bars having locking means and catches adapted to engage the locking means and to be raised by the unlocking means, of a system of superposed wedge plates acting to lock the party levers, 80 a locking bar loosely connected with the catches, an operating bar, a resetting shaft by which said bar is actuated and a special resetting bar co-acting with the wedge system, the locking bar and the operating bar. 85

146. The combination with voting members, party levers, and a system of superposed wedge plates co-acting therewith, of releasing, restricting and resetting mechanisms and a special resetting bar co-acting 90 with said mechanisms.

147. The combination with voting members, party levers, party bars having unlocking means, resetting bars having locking means and catches adapted to engage the 95 locking means and to be raised by the unlocking means, of a locking bar loosely connected with the catches, a special resetting bar, restricting and releasing shafts and connections intermediate said shafts and the 100 locking and special resetting bars.

148. The combination with voting members, party levers, party bars having unlocking means, resetting bars having locking means and catches adapted to engage 105 the locking means and to be raised by the unlocking means, of a system of superposed wedge plates acting to lock the party levers, a locking bar loosely connected with the catches, restricting and releasing shafts, a 110 special resetting bar and connections intermediate said bar and the wedge system, the locking bar and the restricting and releasing shafts.

149. The combination with voting members, party levers, members actuated by the party levers and having unlocking means, and members actuated by voting members and having locking means, of catches engaging the locking means and raised by the 115 unlocking means, a locking bar loosely connected with the catches and a special resetting bar co-acting with the locking bar. 120

150. The combination with voting members, party levers, members actuated by the 125 party levers and having unlocking means, and members actuated by voting members and having locking means, of catches en-

- gaging the locking means and raised by the unlocking means, a locking bar loosely connected with the catches, an operating bar and connections with the members and a 65
 5 special resetting bar co-acting with the locking and operating bars.
151. The combination with voting members, party levers and a system of superposed wedge plates, of restricting and releasing 70
 10 shafts, a special resetting bar, a cam bar by which said bar is actuated and connections intermediate the special resetting bar and the wedge system and restricting and releasing shafts.
152. The combination with voting members, party levers, party and resetting bars and catches adapted to engage the resetting bars and to be raised by the party bars, of a 75
 15 locking bar loosely connected with the catches, restricting and releasing shafts, a special resetting bar and connections intermediate said bar and the restricting and the releasing shafts and the locking bar.
153. The combination with voting members, party levers, party and resetting bars and catches adapted to engage the resetting bars and to be raised by the party bars, of a 80
 20 locking bar loosely connected with the catches, a system of superposed wedge plates, restricting and releasing shafts, a special resetting bar and connections intermediate said bar and the restricting and releasing shafts, the locking bar and the wedge system.
154. The combination with voting members, party levers, party and resetting bars and catches adapted to engage the resetting bars and to be raised by the party bars, of a 85
 25 locking bar loosely connected with the catches, an operating bar and connections with the party and resetting bars, a resetting shaft by which the operating bar is actuated, and a special resetting bar and connections co-acting with the locking and the wedge system.
155. The combination with voting members, party levers, party and resetting bars and catches adapted to engage the resetting bars and to be raised by the party bars, of a 90
 30 locking bar loosely connected with the catches and having an extension, an actuating slide co-acting with said extension, a special resetting bar and connections between said bar and the locking bar.
156. The combination with voting members, party levers, party and resetting bars and catches adapted to engage the resetting bars and to be raised by the party bars, of a 95
 35 locking bar loosely connected with the catches, and an interlocking member co-acting with the voting members.
157. The combination with voting members, party levers, party and resetting bars and catches adapted to engage the resetting 100
 40 bars and to be raised by the party bars, of a locking bar loosely connected with the catches and a system of superposed wedge plates co-acting with the party levers.
158. The combination with voting members, party levers, party and resetting bars and catches adapted to engage the resetting bars and to be raised by the party bars, of a 105
 45 locking bar loosely connected with the catches, interlocking members co-acting with the voting members, a system of superposed wedge plates co-acting with the party levers and a special resetting bar co-acting with the locking bar and the wedge system.
159. The combination with voting members, party levers, party and resetting bars and catches adapted to engage the resetting bars and to be raised by the party bars, of a 110
 50 locking bar loosely connected with the catches, interlocking members co-acting with the voting members, a system of superposed wedge plates, a releasing shaft and connections between said shaft and the locking bar and the wedge system.
160. The combination with voting members, party levers, party and resetting bars and catches adapted to engage the resetting bars and to be raised by the party bars, of a 115
 55 locking bar loosely connected with the catches, interlocking members co-acting with the voting members, restricting members co-acting with the interlocking members, a restricting bar to which the restricting members are detachably connected, and a special resetting bar.
161. The combination with voting members, party levers, party and resetting bars and catches adapted to engage the resetting bars and to be raised by the party bars, of a 120
 60 locking bar loosely connected with the catches, interlocking members, restricting members, a restricting bar to which said members are detachably connected, restricting and resetting shafts and connections between said shafts and the resetting bar.
162. The combination with voting members and party levers, of a cam bar and connections which unlocks the party levers leaving the voting members locked, and superposed wedge plates and connections operated by a party lever to lock the other party levers. 125
163. The combination with party lines of voting members, and party levers, of a cam bar and connections which unlocks the party levers leaving the voting members locked, a system of superposed wedge plates operating in connection with a party lever to lock the other party levers and a party bar operated by a party lever to actuate all voting members in that party line.
164. The combination with voting members, party levers and party bars, of a cam bar and connections to the party bars which 130

unlock the party levers leaving the voting members locked, and superposed wedge plates and connections for locking all other party levers when a party lever is operated.

5 165. The combination with voting members, party levers and party and resetting bars, of catches adapted to engage the resetting bars and to be raised by the party bars and a cam bar and connections which 10 unlocks the party bars.

166. The combination with voting members, party levers, party and resetting bars and catches adapted to engage the resetting bars and to be raised by the party bars, of

15 a locking bar loosely connected with said catches, for the purpose set forth, and entrance mechanism acting to unlock the party bars.

167. The combination with voting members, party levers, party and resetting bars and catches adapted to engage the resetting bars and to be raised by the party bars, of a locking bar loosely connected by the catches, a system of superposed wedge plates 25 co-acting with the party levers and entrance mechanism which unlocks the party bars.

168. The combination with lines of voting members and interlocking members, of restricting members for operating said interlocking members and provided with additional means for locking the voting members in one of said lines, and means for operating said restricting members.

169. The combination with voting members, party bars connecting said members in party lines, and interlocking members, of means for automatically locking said party bars against a second forward movement after a return movement.

40 170. The combination with voting members, party bars connecting said voting members in party lines, party levers, and links connecting said party bars and party levers,

of means engaging said links for automatically locking said party bars against a 45 second forward movement after a return movement.

171. The combination with voting members, party levers, party bars, links engaged by the party levers and having notches, 50 studs connecting the links and the party bars, and resetting bars having elongated slots through which the studs pass, of dogs adapted to engage the notches in the links to lock said party bars against a second forward movement after a return movement.

172. The combination with voting members, party levers, party bars, links engaged by the party levers and having notches, 60 studs connecting the links and the party bars, and resetting bars having elongated slots through which the studs pass, of dogs adapted to engage the notches in the links to lock said party bars against a second forward movement after a return movement, 65 and means for engaging and controlling said dogs.

173. The combination with voting members, party levers, party bars, links engaged by the party levers and having notches, 70 studs connecting the links and the party bars, and resetting bars having elongated slots through which the studs pass, of dogs adapted to engage the notches in the links to lock said party bars against a second forward movement after a return movement, 75 and means for holding said dogs out of engagement with said notches until said resetting bars have been operated.

In testimony whereof I affix my signature 80 in presence of two witnesses.

CHARLES C. ABBOTT.
